UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

NON-INTERFERING EXTENSION PARTY-LINE TELEPHONE SYSTEM.

1,151,544.

Specification of Letters Patent. Patented Aug. 24, 1915.

Application filed November 25, 1905. Serial No. 289,048.

To all whom it may concern:

Be it known that I, TALBOT G. MARTIN, a citizen of the United States of America, and resident of Chicago, Cook county, Illinois, have invented a certain new and useful Improvement in Non-Interfering Extension or Party-Line Telephone Systems, of which the following is a specification.

My invention relates to telephone systems in general, but more particularly to the so-called extension and party-line telephone systems, and especially to automatic or semi-automatic telephone systems of that type in which more or less of the trunking or other switching operations are produced by the calling subscriber without the aid of an operator, and by simply transmitting one or more electrical impulses to the exchange or central station, as for example, by momentarily grounding either one or both sides of the line at the sub-station of the calling subscriber.

In extension and party-line telephone systems of the particular class to which my invention more especially relates, it is evident that if one subscriber is using a line which is common to several subscribers, and if another subscriber on the same line attempts to use his telephone, the connections already established through the medium of said line will be broken—that is to say, the intruding subscriber will, in attempting to use his telephone, operate certain release-circuits and thereby release and restore the switching devices by which the talking circuit was established. Suppose, for example, that one subscriber on a line is in conversation with a subscriber on another line, or with another subscriber on the same line. In such case, the intrusion of a third subscriber in the circuit will, for example, cause a grounding of both sides of the established line-circuit, and thus set up the conditions which are relied upon as a means for restoring the switching machinery by which the circuit was established. In other words, in extension and party-line telephone systems it is always undesirable to have the circuits and apparatus so constructed that a third subscriber can listen-in on an established circuit and thereby overhear the conversation between the two subscribers already in possession of the line; and in automatic or semi-automatic telephone systems of that character in which electrical im-

pulses are used for calling the number of the called subscriber, and for releasing the switching machinery after the subscribers are through talking, it is important and practically necessary I find that some provision be made whereby when any two subscribers are using a line a third subscriber cannot then manipulate his telephone switching devices in such manner as to break or interfere with the circuit established between the said talking subscribers. It is obvious that this is true of either the so-called extension telephone arrangements in which several extension telephones are connected with a main or master telephone, or of the ordinary party-line arrangement in which several subscribers are simply bridged across a telephone line and not subject to the supervision of an operator at a main or master telephone.

Generally stated, therefore, the object of my invention is the provision of an improved and highly efficient extension or party-line telephone system so constructed that the different subscribers occupying a line in common cannot interfere with each other in the use of such line—that is, so constructed that when one subscriber has the line he may use it without any possibility of being disturbed or molested by any other subscriber.

Special objects of my invention are the provision of an improved lock-out device for party-line telephones, whereby if one subscriber is using the line no other subscriber on the same line can use the latter for either switching or signaling purposes; the provision of an improved construction and arrangement whereby several subscribers may be connected with a single line in an automatic or semi-automatic telephone system, and whereby if one subscriber is using the line no other subscriber on the same line can transmit any electrical impulses, either for switching or signaling purposes, or do anything which will endanger the continuity of the talking circuit established by the subscriber already in possession of the line; the provision of an improved construction and arrangement whereby the different sub-stations on a party-line in an automatic telephone system may each be provided with a lock-out or cut-off relay of such character that no subscriber on the line can transmit any electrical impulses, either for switching

or signaling purposes, while the talking circuit is temporarily in use by some other subscriber on the same line; the provision of a non-interfering party-line or extension telephone system including "first-selectors" which are each provided with a special set of so-called off-normal-springs which are controlled by the "selector-shaft," and by means of which the so-called rotary-line-conductor is maintained normally disconnected from the non-grounded terminal of the battery, or other centralized source of current, until after the shaft of the "selector" is raised from its normal position; the provision of an improved construction and arrangement, involving special relays in the "first-selectors," and improved circuit connections, whereby a party-line subscriber may call his own line, so to speak, so as to obtain connection with the sub-station of some other subscriber on the same line; and the provision of certain details and features of improvement tending to increase the general efficiency and serviceability of party-line and extension telephone arrangements of this particular character.

To the foregoing and other useful ends, my invention consists in matters hereinafter set forth and claimed:

30 In the accompanying drawings, Figure 1 is a diagram showing two party-lines connected together. One of said lines is provided with two sub-stations (#110 and #210) that are bridges in multiple across the line-conductors, and the other is provided also with similar stations (#120 and #220). One of said lines is shown connected through a "first-selector" C and a "connector" D with the other of said lines, which latter has bridged across it a second "first-selector" E. All of the substations shown are identical, as well as all of the "first-selectors." Fig. 2 is a front elevation of a sub-station keyboard mechanism, showing the dial-plate removed and the switch-hook raised. Fig. 3 shows the same mechanism with the switch-hook down. Fig. 4 is a diagrammatic perspective view of the "first-selector" C, showing the approximate relative positions of its parts, the switch-frame not being shown. Fig. 5 is a similar view of the "connector" D. Fig. 6 is a view similar to Fig. 1, in which the subscriber at station #310 has called and connected with the station #110, on the same line, through the "first-selector" C and the "connector" D, the station #210 being bridged across the line between sub-stations #310 and #110.

60 All such sub-stations are provided with the usual details essential to subscribers' stations of the class in question. Sub-station #110, for instance, is provided with a receiver 2 and a switch-hook 3, which latter has radiating from its body a number of cam-arms 4, 5, 6 and 7, said hook being pivotally secured to the keyboard frame by the screw 8 about which it rotates when the receiver is removed. The rotation is due to the tension of a spring that is not shown and the hook is pushed up for the purpose of changing certain circuit connections to be disclosed. Furthermore, said sub-station has a transmitter 9, a local battery 10, a ringer 11, an induction-coil 12 with a primary winding 13 and a secondary winding 14, a condenser 15, a lock-out magnet 20, and in addition a signaling device comprising a button 16, a spring 17, and two contact-points 18 and 19. When the switch-hook is down, the cam-arm 4 is held in contact with the spring 21, thereby flexing the said spring in a downward direction. Said spring is normally in contact, therefore, with the arm 4, and in this way completes the ringing circuit which includes the ringer 11 and the condenser 15, the latter being normally bridged across the line in series. Associated with the spring 21 are two sets of springs 22 and 23, and 24, 25 and 26. Members of each of these sets, when left to their own tension, when the switch-hook is up, engage in contact with each other—that is, the springs 22 and 23 are then in contact, and the springs 24, 25 and 26 are in contact; but whenever the switch-hook depresses the spring 21 the latter permits the springs 22 and 23 to separate and forces, at the same time, the springs 24, 25 and 26 apart, through the medium of an insulating washer 27 located between the springs 21 and 26. The arm 7, when raised, forces the spring 28 away from the spring 29, while the arm 6 permits the spring 30 (which is normally disengaged from the spring 31) to close in contact with the latter. Whenever the switch-hook is drawn down, the three springs 32, 33 and 34, which are known as the release-springs, are forced into union by the arm 5 on said switch-hook, which arm engages a laterally-projecting piece that constitutes the top extremity of the spring 32 of this group of springs. However, when the switch-hook nears its lowermost position the said arm disengages from said spring and permits the three to again disengage. The calling device is represented by two push-buttons 35 and 36, two springs 37 and 38, two contact-points 39 and 40, and the ground post 41. The lock-out magnet, as most clearly shown in Fig. 2, consists of the coil 20 mounted upon a supporting plate 55, which latter is secured to the keyboard frame 42. This magnet is provided with a yoke 43 which acts as a support for the armature 44, which latter is pivoted at 45. Said armature, through the medium of an elongated arm 46 which carries at its extremity an insulating pin 47, is so mechanically constructed that whenever the magnet is energized the spring 48 which normally

totally secured to the keyboard frame by the screw 8 about which it rotates when the receiver is removed. The rotation is due to the tension of a spring that is not shown and the hook is pushed up for the purpose of changing certain circuit connections to be disclosed. Furthermore, said sub-station has a transmitter 9, a local battery 10, a ringer 11, an induction-coil 12 with a primary winding 13 and a secondary winding 14, a condenser 15, a lock-out magnet 20, and in addition a signaling device comprising a button 16, a spring 17, and two contact-points 18 and 19. When the switch-hook is down, the cam-arm 4 is held in contact with the spring 21, thereby flexing the said spring in a downward direction. Said spring is normally in contact, therefore, with the arm 4, and in this way completes the ringing circuit which includes the ringer 11 and the condenser 15, the latter being normally bridged across the line in series. Associated with the spring 21 are two sets of springs 22 and 23, and 24, 25 and 26. Members of each of these sets, when left to their own tension, when the switch-hook is up, engage in contact with each other—that is, the springs 22 and 23 are then in contact, and the springs 24, 25 and 26 are in contact; but whenever the switch-hook depresses the spring 21 the latter permits the springs 22 and 23 to separate and forces, at the same time, the springs 24, 25 and 26 apart, through the medium of an insulating washer 27 located between the springs 21 and 26. The arm 7, when raised, forces the spring 28 away from the spring 29, while the arm 6 permits the spring 30 (which is normally disengaged from the spring 31) to close in contact with the latter. Whenever the switch-hook is drawn down, the three springs 32, 33 and 34, which are known as the release-springs, are forced into union by the arm 5 on said switch-hook, which arm engages a laterally-projecting piece that constitutes the top extremity of the spring 32 of this group of springs. However, when the switch-hook nears its lowermost position the said arm disengages from said spring and permits the three to again disengage. The calling device is represented by two push-buttons 35 and 36, two springs 37 and 38, two contact-points 39 and 40, and the ground post 41. The lock-out magnet, as most clearly shown in Fig. 2, consists of the coil 20 mounted upon a supporting plate 55, which latter is secured to the keyboard frame 42. This magnet is provided with a yoke 43 which acts as a support for the armature 44, which latter is pivoted at 45. Said armature, through the medium of an elongated arm 46 which carries at its extremity an insulating pin 47, is so mechanically constructed that whenever the magnet is energized the spring 48 which normally

rests against said insulating pin is pressed away from an adjoining spring 49. Furthermore, said magnet carries on its underside an armature locking device that consists preferably of a brass piece 50 which is normally horizontally disposed and which is riveted to a spring 51 that is fastened to the rear end of the magnet frame. The front end of said brass piece is bent at a right angle upward, and then at a right angle to the front, so that whenever the armature 44 is attracted by the magnet the spring tension in the spring 51 forces the brass member upwardly until the angled section rises in front of the armature 44 and locks it in its attracted position. The switch-hook also carries an angled plate 52 which has a projecting section at the end of which latter a slim rod 53 is hooked. This rod is very light and passes through an opening in the front part of a guide-post 54 which is supported upon the magnet yoke 43. The lower end of said rod works in front of the armature 44 and is bent at a right angle horizontally and in a plane parallel with the surface of the armature. When the switch-hook is depressed the said link is pushed down far enough to drive the lock 50 below the edge of the armature 44, which latter then, if the magnet is not energized, resumes its normal position, as shown in Fig. 3. When said armature is restored the lock-out magnet-springs 48 and 49 resume their normal engagement.

As stated, the "first-selector" is shown in Fig. 4, and may be of the general type described in Patent No. 815,321, granted March 13, 1906, to Keith, Erickson & Erickson. This form of selector was well known before the date of my application. It embodies among other details the following well known devices and circuits: the switch-shaft 100, which is situated on the front part of the switch, and on the lower section of the said shaft the line-wipers 101 and 102 are fastened, and just above them is a private-wiper 103. These wipers are all not only insulated from each other, but from the shaft as well. The positions of the wipers are opposite their respective banks—the line-wipers oppose the line-bank 104, and the private-wipers oppose the private-bank 105. At its middle portion the shaft carries a cam 106 which, being of a split sleeve design, is tightened to the shaft by a screw 107. Above the cam is a hub-like piece 108 that has a large lower section on which a number of longitudinal or rotary teeth 109 are provided. The upper section of this hub is smaller than the lower and has formed in it a set of circular or vertical teeth 110 which are traversed by a groove or slot 111. This groove 111 is designed to receive the bent end of the so-called shaft support 112 which prevents the

shaft from rotating unless said end is opposite one of the grooves between the circular teeth. Still higher up the switch-shaft has fastened to it an arm-like guide 113 which, when the shaft is in its lowest position, keeps the off-normal springs 114 and 115 separated from the contact-points 116 and 117, respectively. Normally, the shaft is kept in its rotary position by the coiled spring 118, which latter has its inner end fastened to the shaft 100 and its outer end to the guide-pin 119. The supporting bearings of the shaft are not shown, but one of such bearings is located between the private-wiper 103 and the cam 106, and the other between the upper end of hub 108 and guide-arm 113. These bearings are fitted to the switch-frame. The movements of the shaft are vertical and rotary and each movement must take place at a different time. By these movements the wipers may be carried into engagement with any one of the hundred terminals or sets of contact-points that constitute the private and line banks. Since these contacts are arranged in ten vertical and ten horizontal rows, the shaft is made to admit of ten vertical steps and at each level of ten rotary steps.

The movements of the shaft are attained by means of the vertical and rotary line-relays 119 and 120 and through their respective armatures 121 and 122 which control the springs 123, 124 and 125. Normally, the switch-shaft rests so that the wipers are one step lower than the lowest level of their respective banks, and one step to the left of them. Now, when the vertical-line-relay is magnetized, the vertical-magnet 126, which is composed of two coils 127 and 128, is also magnetized. This last magnet has an armature 129 known as the vertical-armature and which has projecting from it a so-called vertical-arm 130 that has pivotally fastened to its end a pawl 131, known as the vertical-pawl, which is properly adjusted to engage one of the circular teeth 110 at each vertical movement of the vertical-armature. This vertical-pawl is held in normal position by the retracting-spring 132 suitably fastened by one end to the back of the pawl 131 and by the other to the vertical-arm 130. The vertical-armature is provided also with a retracting-spring 133 between the pawl 131 and said vertical-armature that maintains the latter in its position of rest. The vertical-arm carries an L-shaped piece 134 on its underside that assists in the unlocking of the switch when it is first brought into use. This L-shaped piece 134 projects under a link 135 known as the release-link, which latter is fastened by one end to the armature 136 of the release-magnet 137. The release-magnet has assigned to it the function of restoring the switch to its normal position.

after it has been operated. This magnet is composed of two coils, like the vertical-magnet, but only one coil is shown. The release-armature, like the armature of all of the other magnets, is suitably supported, and is kept in normal position away from the release-magnet pole-piece by a retracting-spring 138.

The forward end of the release-link 135 broadens out, and at this broadened section 10 a square opening 139 normally engages with a lug 140 on the double-dog 141. This double-dog is pivoted on the switch frame by the pivots 142, and formed on its front part 15 are two dogs 143 and 144 that are designed, the first one to engage with the circular teeth 110, and the last with the longitudinal teeth 109. From the lower side of the double-dog a release-arm 145 projects downward and assists in the restoration of the side-switch when the switch is released. The side-switch comprises a supporting member 146 known as the side-switch arm. It is pivoted and may be moved about a vertical axis passing through the pivots 147. To the left of the pivots the arm 148 extends rearwardly, and on the end of this arm the side-switch-link 149 is pivotally secured by one end and at its other engages 30 the lower end of the release-arm 145, the end of the latter being of an inverted T-shape, while the end of the former is bifurcated. Still nearer to the end on the same side, the side-switch-arm 146 carries a pin 150 which 35 binds into one piece four wipers 151, 152, 153 and 154 known as the side-switch-wipers. These wipers are insulated from each other and from the supporting pin to which they are all rigidly fastened. The 40 said wipers being rigid with the pin, and the pin being also rigid with the side-switch-arm 146, it follows that when the side-switch-arm is rotated about the pivots 147 switch-arm is rotated about the pivots 147 the side-switch-wipers will move also. The 45 right hand end of the side-switch-arm is drawn out into a finger 155, known as the escapement-finger, that works in conjunction with a tooth-escapement to be described. At the base of this finger a forwardly-bent lug 156 limits the swivel movement of the side-switch-arm, and, therefore, 50 of the side-switch as a whole, by striking the cam 106 whenever the shaft is rotated out of its normal rotary position. If the 55 rotary-line-relay is energized the private-magnet 160 is energized as a result. This last magnet is usually fastened to a small private-magnet frame that is not shown and which is fastened to the main switch frame. Said magnet has an armature 161 that works 60 in a vibratory manner about a horizontal axis that passes through the supporting points 162. The said armature is formed with a forwardly-projecting arm 163 having two flat surfaces in an approximately

horizontal plane. Furthermore, the end of the said arm is bent at a right angle downwardly and carries certain mechanical details, namely, a lateral arm 164 which is designed to control the relation of the private-springs 165, 166 and 167 and a tooth-escapement which includes two flexible springs 168 and 169 each of which is riveted by one end to the arm 163, one on the upper side and the other on the lower. The upper 75 spring is straight and has formed on its end a couple of tooth-projections 170 and 171 which extend downwardly, while the under spring is bent at a right angle first down and then at a right angle to the front. This 80 double angle on the lower spring is so designed that the latter may clear the bent portion of the private-arm, against which portion said spring rests with a degree of tension. There is space in front of said 85 bent portion to receive two other tooth-shaped upwardly-projecting pieces 172 and 173 that are formed on the forward end of the escapement-spring and which are sustained in juxtaposition to the upper teeth, 90 but slightly to the rear thereof. A retracting-spring 174, which has one end attached to the private-armature and the other end to the switch frame, holds said armature 95 normally away from the private-magnet pole-piece. With this construction when the private-magnet is energized once, the private-armature is drawn down momentarily and restored. By this operation the escapement-finger 155 passed first from behind the tooth 172 onto the rear of the tooth 170, at the downward stroke of the private-armature, and from behind the latter tooth at the return stroke. As soon as the escapement-finger clears this last tooth, the retracting-spring 213 draws the side-switch 100 to the second position where it is stopped by the lug 156 striking the cam 106.

When the side-switch-wipers pass to the second position, leaving the contact-points 110 175, 176, 177 and 178, and engaging instead with the contact-points 197, 198, 199 and 200, the rotary-magnet 179 is energized, this magnet being composed of two coils 180 and 181. The rotating mechanism consists of 115 the rotary-armature 182, a circuit interrupting arm 183 that works in conjunction with two interrupter-springs 184 and 185, the rotary-armature-finger 186 that exercises certain controlling influences over the private-armature, and lastly the rotary-arm 187. This arm carries pivotally attached to its forward end the so-called rotary-pawl 188. Said pawl has attached to its rear end a small coiled spring 189, the other end of 120 which latter is fastened to the rotary-arm, and which always restores the rotary-pawl to its normal position. Upon each rotary step of the shaft the rotary-locking-arm 144 falls behind one of the longitudinal teeth 125 180

and locks the shaft. Said locking-arm and teeth form the locking device. When the rotary-armature is attracted the rotary-pawl 188 engages with the longitudinal-teeth 109 and the shaft is rotated until the rotary-armature 182 strikes the rotary-magnet pole-pieces. The energizing circuit of the rotary-magnet passes through the interrupter-springs 184 and 185, and when the rotary-armature is attracted they are separated by the interrupter-finger 183. When the energizing circuit is broken the rotary-armature is drawn to its normal position by the rotary-armature retracting-spring 190. Attention has been called to the banks that are located under the switch parts in position before the line-wipers and the private-wipers. The private-contact-terminals are each composed of but one electric conducting piece, but the line-contact-terminals are each made of two metallic pieces, one over the other and insulated from each other. When the shaft is raised and rotated, the wipers engage with the contacts of their respective banks, the private-wiper with those of the private-bank, and the line-wipers with those of the line-bank. After a switch has been operated it can be released by the energization of the release-magnet 137, which energization results if the line-relays 119 and 120 are magnetized simultaneously, or if the back-release-relay 191 that controls the back-release-relay-springs 192 and 193 is energized. The circuits that are brought into play under these conditions will hereinafter be more fully explained. When the release-armature is drawn back after the release-magnet loses its magnetizing force, the double-dog is drawn away from the shaft. Said shaft when raised and rotated rests on the shaft-rest 112, as previously stated, and when left to the back pull of the coiled spring 118 rotates on the said shaft-rest until the stop-arm 113 strikes the guide-post 119^a. The shaft-rest then enters the channel 111 that traverses the circular teeth, and leaves the shaft to fall to its normal position by reason of its own weight. The vertical-line-conductor that leads to the "first-selector" C terminates in the side-switch-wiper 153, and to the same side-switch-wiper the vertical-normal-conductor 194 is connected, which normal-conductor leads to and terminates in multiple-contacts in connector-banks. The rotary-line-conductor 465 of the same line terminates in the off-normal spring 116 which is normally out of contact with the corresponding spring 114, both of which springs are in engagement whenever the switch is off-normal. The spring 114 connects with the rotary-side-switch-wiper 154. It will be noticed, therefore, that between the rotary-line-conductor and the rotary-side-switch-wiper there is a contact which is normally open while the switch is not in use. The rotary-normal-conductor 195, which also terminates in multiple-contacts in connector-banks, is connected with the off-normal spring 116, and is therefore disconnected from the rotary-side-switch-wiper 154. It will be noticed that, like the vertical and rotary normal conductors 194 and 195, the private normal conductor 196 also terminates in multiple-contacts at connector-banks, and at the selector C in the private-side-switch-wiper 152, after passing through certain private normal springs.

The side-switch-wipers 151, 152, 153 and 154, when in the second position, are in engagement, respectively, with the contact-points 197, 198, 199 and 200; and when in the third position these side-switch-wipers are in engagement with the contact-points 201, 202, 203 and 204. Between the contact-point 204 and the rotary line wiper 101 the private-normal-relay 205 is located and provided with an armature 206 which controls the private-normal-relay-springs 207 and 208, so as to insure the operations herein-after described. The "first-selector" is, in addition, provided with a bridge-cut-off-relay 209, the armature 210 of which relay has the power to separate the bridge-cut-off-relay-springs 211, 212 and 213. The two former of said springs constitute the terminals of the vertical and rotary line-relays 119 and 120, respectively, while the latter is connected directly with the nongrounded terminal of battery B. When the bridge-cut-off-relay is energized these three springs are separated one from the other, thereby opening the bridge formed between side-switch contact-points 177 and 178, through said line-relays, and at the same time interrupting the connection between said relays on the other side and the non-grounded terminal of the battery. If for any reason the switch-shaft 100 is raised then when the off-normal spring 115 closes with the contact-point 117 a circuit is closed through a signal-lamp 214. The retention of said shaft in a raised condition uselessly is undesirable since each station that tries to call while it is raised is locked out for the time. The light signal is designed as a notice to the switchboard man in charge of the exchange of any irregularity of such a nature.

Fig. 5 shows the "connector" which has many parts and circuits very similar to those of the "first-selector," and the general movements are nearly identical. The "connector" may be of the general type described in Patent No. 815,176, granted March 13, 1906, to Keith, Erickson & Erickson. This form of connector was well known before the date of my application. To the vertically-disposed switch-shaft 250 are secured the vertical and rotary line-wipers 251 and 252 which are insulated from each

other and from the shaft, and also the so-called private-wiper 253, the latter being also insulated from the shaft. A cam or side-switch stop device 254 is secured near the middle portion of the said shaft, and above the said cam is arranged the hub-like piece 255 upon which are mounted the longitudinally-extending ratchet-teeth 256, as well as the circular ratchet-teeth 257. The latter are located just above the rotary ratchet-teeth, and are traversed by a longitudinal groove or channel 258, and in order to correspond with the number of levels shown in the bank 259, the said teeth are preferably ten in number, so that the shaft may be given ten successive vertical steps, and so that it may be thus at each step placed at one of the ten levels. At each level, by means of the longitudinal teeth, the shaft may be rotated ten steps. The said line-wipers 251 and 252 are adapted to coöperate with the bank-terminals 259, and these terminals are arranged, of course, in ten horizontal rows of ten terminals each, in the usual and well-known manner. The private-wiper 253 is adapted, on the other hand, to coöperate with the bank of private-contacts 260. At its upper end the said shaft is subject to the action of a clock-spring 261 which has one end secured to said shaft and the other to the stop or normal-post 262, whereby the shaft when rotated winds up said spring, and whereby when the switch is released said shaft may be automatically restored to its normal position from any position in which it may have been temporarily held for the purpose of maintaining any desired electrical connection. The shaft is also provided at its upper end portion with the guide-arm 263 which normally keeps the spring 264 out of engagement with the stationary switch-contact 265, which latter constitutes one terminal of the well-known busy machine F—that is, the machine for producing the current used for giving the busy signal to a calling subscriber when necessary. Before the shaft is rotated from its normal position, the groove or channel 258 is engaged by the end of the hook-shaped arm or stationary shaft-rest 266; but with the shaft raised to some desired level, and as soon as it is rotated, the circular tooth at such level then slides onto said rest and rotates upon it instead of on the vertical-dog 267. Thus the said rest acts not only as a bearing, but as a support for the shaft as well.

The vertical and rotary line-relays 268 and 269 are bridged across the trunk-line-conductors in front of the condensers 270 and 271, as clearly shown, with the non-grounded pole of battery B connected to the said bridge at a point between the two relays 268 and 269. The vertical-magnet 272 is controlled by the vertical-line-relay

268 and arranged to operate the vertical-ratchet-pawl 273, which latter is pivotally mounted upon an arm 274 rigidly secured to the armature 275. This armature 275 vibrates about the points 276. The vertical-arm 274 is provided with a short L-shaped arm 277 for operating the release-link 278. The latter, like the release-link of the "first-selector," has an opening 279 which normally engages the projecting pin 280 on the double-dog 281. The said vertical-arm is normally retained away from the vertical-magnet pole-pieces by a retracting-spring. The double-dog is provided with a locking member 267 adapted to engage the circular teeth 257, and also with another locking member 282 adapted to engage the longitudinal ratchet-teeth 256 whenever the double-dog is released from the release-link 278. The said double-dog is subject to the spring tension that tends always to force said projecting members or dogs into engagement with the said ratchet-teeth, and is provided in addition with a downwardly-extending arm 283 having a T-shaped end 90 portion 284 adapted to support the bifurcated end of the link 285, which latter has its other end pivotally connected with the end of a rearwardly-projecting member 286 on the side-switch-arm 287. The said side-switch-arm is swingingly mounted and provided with the usual side-switch-wipers 288, 289, 290 and 291, and is subject to the forward tension of the spring 292. The side-switch-arm with its appended parts constitute the well-known switch. The so-called rotary-magnet 293 has an armature 294 pivotally mounted at 295 and carries a rigid arm 296 upon the end of which the rotary-pawl 297 has its support, the latter being pivotally mounted upon said arm 296. It will be seen that the pawl 273 is adapted through the circular ratchet-teeth 257 to actuate the shaft vertically while the pawl 297 is adapted with the aid of the longitudinal teeth to actuate the shaft rotatively. Both the vertical and rotary magnets are connected directly with the non-grounded pole of the battery and are controlled by the vertical-line-relay 268, subject, however, to the switching action of the side-switch-wiper 288. The so-called private-magnet 298 is provided with the armature 299 having two flexible springs 300 and 301 which are provided, the upper one with one tooth 303, and the lower one with two teeth 304 and 305. With the exception of the spring 300 having only one tooth the escapement device of the "connector" is identical with that of the "first-selector." All of the armatures of the different magnets in the "connector," like those of the "first-selector," are held normally away from their respective magnets by springs of suitable character and suitably located. The arm 306 of the private-arm- 130

ture is provided with an insulating piece 307 that engages with the private-springs 308, 309, 310 and 311 as a whole, and which is adapted to flex the springs 309 and 310 up and down. These two springs are riveted together, but kept from electrical connection by any suitable insulating material. When the private-armature is depressed the springs 308 and 309 are separated and the 5 springs 310 and 311 are pressed into contact; while if the private-armature is raised the reverse occurs with the springs 308 and 309 retained in contact. The side-switch-arm 287 is drawn out at one end to form the 10 finger 312 known as the escapement-finger and adapted to coöperate with the escapement-teeth in releasing the side-switch from first to second position, in a well-known manner, and then from second to third position 15 when the private-armature is depressed. The release-magnet 313 has an armature 314 adapted, when attracted, to restore the double-dog 281 to its normal position—that is, to a position where the circular and vertical dogs 282 and 267 are held out of engagement with their respective ratchet-teeth 256 and 257. The side-switch-wipers 291 and 290 are adapted when shifted to third position to establish connection between the 20 line-conductors 483 and 482 and the line-wipers 251 and 252, respectively. The ringing-relay 315, by means of its armature 316, controls through the medium of the ringer-relay-springs 317, 318, 319, 320, 321, 322, 25 323 and 324 a number of circuits among which are the connections between the condensers 271 and 270 and the wipers 251 and 252. After the "connector" has completed a call and the ringer-relay is energized when 30 the calling subscriber presses his signaling-button and by so doing removes his own line-conductors from the established circuit and substitutes instead the terminals of the ringer-generator H across the wipers 252 and 251 and hence across the subscriber's 35 line for the purpose of signaling the called subscriber. The side-switch-wiper 289 is adapted when shifted into third position to connect the private-wiper 253 with the 40 grounded side-switch-contact 325. The side-switch-wiper 288 is adapted when shifted into third position to connect with the ringer-relay 315, the terminal of which relay is permanently connected to the contact-point 326.

In Fig. 1 the called "first-selector" E being identical to the calling "first-selector" C the parts will be recognized upon reference. The vertical and rotary line-relays 401 and 402 are bridged between the side-switch contact-points 403 and 404 with which the vertical and rotary side-switch line-wipers 405 and 406 respectively engage while the side-switch is in the first position. 45 These two relays are connected normally,

while the bridge-cut-off-relay is deenergized, through the bridge-cut-off-relay-springs 407 and 408. At this point where two springs are thus in contact a third spring 409, connected with the non-grounded terminal of the battery B, maintains a connection between the line-relays and the battery. Connected to the vertical and rotary line side-switch-wipers 405 and 406 are the vertical and rotary normal-trunk-conductors 501 and 502 that are connected with the "connector" line-bank-terminals. The private-normal-relay 412 has control of the private-normal-relay-springs 413 and 414 through which the private-normal-conductor 507 is connected with the private-side-switch-wiper 416. Said side-switch-wiper constitutes the terminal of the back-release-relay 417. The private-normal-conductor terminates in the "connector" private-banks in private-contact-points that correspond to the "connector" line-bank-terminals in which the normal-conductors 501 and 502 terminate. In the "first-selector" C similar normal-line-conductors are indicated at 194 and 195 and the private-normal-conductor at 196.

In Fig. 1 sub-stations #120 and #220 are substantial duplicates of the sub-station #110. Assuming that the four sub-stations shown in said figure have all of their receivers on their respective switch-hooks, as indicated at station #220; then if the subscriber at sub-station #110 wishes to call the subscriber at sub-station #120 he proceeds first to remove his receiver 2 from the hook 3. Said switch-hook is forced up about the bearing 8, and when the ground springs 30 and 31 close into contact the ground post 41 is thereby placed in connection with the ground terminal G¹. The circuit that completes this connection extends from the ground post 41 along the conductors 450 and 451, through the ground springs 31 and 30, conductor 452, lock-out springs 48 and 49, conductor 453, to the ground terminal G¹. In the next operation the calling subscriber presses the vertical-button 36 once and the rotary-button 35 once, then again the vertical-button twice, and the rotary-button once, and for the last time the vertical-button ten times, and the rotary-button once. In this way, the "first-selector" C is connected with a "connector" D and the latter is then connected by way of the "first-selector" E with a line that leads to the substation #120. When the vertical-button 36 is pressed once for the first digit the vertical-line-conductor 454 is grounded once, since the spring 38, which is removed from contact with the contact-point 40, is brought into contact with the ground post 41. Each time the vertical-line is thus grounded at this stage the vertical-line-relay 119 of the "first-selector" C is energized.

gized once, and as a result the relay-armature 121 is attracted once. The path that the current takes through said relay extends from ground terminal G^1 through a circuit 5 already described to the ground post 41, thence through spring 38 to the vertical-line-conductor 454 and through the side-switch-wiper 153, contact-point 177, conductor 455, vertical-line-relay 119, conductor 456, bridge-cut-off-relay-springs 212 and 213, conductors 457, 458 and 459 to the non-grounded terminal of battery B and to ground G. The vertical-line-relay-armature is operated once and presses spring 123 into 10 contact with the ground spring 124, and thus completes a second circuit through the vertical-magnet 126, which energizes the latter. The current in this case passes from the ground terminal G^2 through the springs 124 and 123 and through the conductor 460 to the private-springs 166 and 165, thence through the conductor 461, vertical-magnet 126, conductors 462, 463, 464 and 459 to the non-grounded terminal of battery B and to ground G. The vertical-magnet attracts its armature 129 once and raises the shaft 100 one step in the manner already described. It may be stated at this juncture that if the calling subscriber decides not to complete 15 the call he may restore the "first-selector" thus disturbed, by simply restoring the receiver to the switch-hook.

It has been described that in its action the switch-hook, through the release-cam-arm 35 5, as it passes down, flexes the release-springs 32, 33 and 34 into contact for a moment. One of said springs—spring 32—has the shape, somewhat, of an inverted L, and it is so located that as the cam-arm descends 40 the latter engages the protruding section of said spring, pressing it to one side, and through it pressing the other two springs 33 and 34 for a moment into electrical contact. The temporary union or engagement of 45 these three springs causes the rotary and vertical line-conductors 454 and 465 to be momentarily grounded at the same time. The effect of grounding the vertical-line-conductor is already known. The rotary-line-conductor thus grounded, after the 50 "first-selector" switch-shaft 100 is raised from its normal position (by which act the guide-arm 113 permits the springs 114 and 116 to come into contact) causes the rotary-line-relay 120 to be magnetized. The path 55 of the current through the vertical-line-relay, in this case, is from ground terminal G^1 through the conductor 453, lock-out relay-springs 49 and 48, conductor 452, ground 60 springs 30 and 31, release-springs 34, 33 and 32, conductor 466 to the contact-point 40 and the spring 38 to the vertical-line-conductor, and thence through the vertical-line-relay 119, as above. The circuit through the 65 rotary-line-relay extends from the same

ground terminal G^1 to the release-spring 34 and thence to the release-spring 33 and through the conductors 467, 468 and 469 to the contact-point 39, over the spring 37 to the rotary-line-conductor 465, off-normal 70 springs 116 and 114, conductor 470, side-switch-wiper 154, contact-point 178, conductor 471, rotary-line-relay 120, conductor 472, bridge-cut-off-relay-springs 211, 212 and 213, to the non-grounded terminal of battery B and to ground G. Whenever the rotary-line-relay 120 becomes magnetized its armature 122, when attracted, forces the spring 125 against the ground spring 124, and thus closes a second circuit that includes the private-magnet 160. The circuit extends from the ground terminal G^2 through the springs 124 and 125, conductors 473 and 474, thence through the private-magnet 160, and through the conductors 475, 476 and 459, thence to the non-grounded terminal of battery B and to ground G. The private-armature being attracted by the private-magnet causes the arm 164 to withdraw the spring 166 from engagement with the spring 165 and closes it instead with the third spring 167. Therefore, when the release is initiated, the line relays 119 and 120 become energized simultaneously; and since the private magnet 160 energizes as a 90 result of the energization of the rotary line relay, the energizing circuit for the vertical magnet 126 is broken when the private springs 165 and 166 separate, and, therefore, the said vertical magnet 126 does not energize at the release. But as the private spring 166, which is connected directly with the line relay spring 123, is shifted into engagement with the private spring 167, the operation of the vertical line relay 119 causes 105 the energization of the release magnet 137, since the private spring 167 is directly connected to said release magnet. It is the vertical line relay 119, therefore, that directly causes the energization of the release magnet 137 by establishing a circuit from the ground terminal G^2 through the line-relay-springs 124 and 123, conductor 460 to the private-spring 166, as before; but from here it then takes a new path through the lower 115 private-spring 167, to the conductor 476 and 477, and to the release-magnet 137, and thence over the conductors 462, 463, 464 and 459 to the non-grounded terminal of battery B and to ground G. Of course, as already 120 pointed out, when said release-magnet becomes magnetized it attracts the release-armature 136 and throws the release-link 135 over the lug 140 of the double-dog 141 which, as soon as the release-magnet becomes 125 deenergized, is rotated about the pivots 142 by the release-armature as it returns to its normal position under the pressure of the retracting-spring 138. This movement causes the removal of the vertical-dog 143 130

from engagement with the circular ratchet-teeth 110. The shaft thus being deprived of its only support falls to its normal or lowered position and the release or restoration of "first-selector" is accomplished. It will be assumed, however, that the subscriber instead of releasing continues his call by pressing the rotary-button 35 once after the "first-selector-shaft" has been raised one step. Under such conditions, the rotary-line-relay 120 is then magnetized once by a current flowing from the ground terminal G⁴ to the ground post 41, thence through the spring 37 to the rotary-line-conductor, and through the rotary-line-relay to the non-grounded terminal of battery B and to ground G. The energization of this relay causes the magnetizing of the private-magnet 160. Upon the downward stroke of the private-armature 161, the escapement-finger 155 disengages from the rearmost tooth 172 of the escapement on the private-armature and falls against the upper rearmost tooth 170 from which the said escapement-finger 155 disengages in turn as the private-armature returns to its normal position. Clearly, at this instant the side-switch is drawn into the second position by the retracting-spring 215, and the lug 156 strikes the cam-piece 106, by which means the side-switch-finger is retained between the escapement-teeth 173 and 172.

At the instant that the side-switch-wiper 151 closes with the contact-point 197, the magnetizing circuit through the rotary-magnet 179 is completed from ground G³ to the contact-point 197, thence through the side-switch-wiper 151, conductor 478, the rotary-magnet-coil 181, interrupter-springs 184 and 185, rotary-magnet-coil 180, conductors 463, 464 and 459 to the non-grounded terminal of battery B and to ground G. The rotary-armature 182 is thus attracted by the rotary-magnet 179 and the shaft 100 is rotated one step by the rotary-pawl 188. At the same time the private-armature is depressed by the rotary-armature-finger 186, and the interrupter-finger, just as the rotary-armature strikes the rotary-magnet 50 pole-pieces, separates the interrupter-springs 184 and 185 and thus interrupts the magnetizing circuit. By the time that the circuit is interrupted, however, the dog 144 has engaged with the longitudinal teeth 109, falling behind the first one of said longitudinal teeth and locking the shaft in the first step of its rotary motion with the shaft-wipers in engagement with the first contact of the first level of their respective banks. 60 When the rotary-armature-finger depresses the private-armature the escapement-tooth 173 is drawn below the lower edge of the escapement-finger and the latter then falls into engagement with the upper foremost tooth 171 from which it disengages as soon

as the private-armature is restored by the rotary-armature retracting-spring 190. As soon as the side-switch-finger clears the escapement-teeth, it is drawn forward into the third position where it meets the side-switch-stop 216. As the rotary-armature returns to its normal position the interrupter-springs will again reengage and the energizing circuit through the rotary-magnet would be reestablished were it not that by 70 the time that the reengagement occurs the private-armature escapement has permitted the side-switch to pass into third position, and, therefore, the side-switch-wiper 151 is no longer in contact with the contact-point 197. As soon as the side-switch passes into third position the private-wiper 103 is connected to ground through the conductor 479, back-release-relay 191, conductor 480, side-switch-wiper 152, contact-point 202, to ground G⁴. This connection to ground provides the private-contact-point with which the private-wiper is connected with guarding potential, as well as all other private-contact-points connected therewith in multiple. It will be seen that as the shaft is rotated by the rotary-armature the vertical-locking-dog 143 is withdrawn from engagement with the circular teeth 100 when the said rotary-locking-dog rides toward the 95 crest of the longitudinal tooth over which it must pass. But at the same time the rest 112 moves into engagement with the circular teeth and furnishes a support for the shaft, in lieu of said vertical-locking-dog, 100 and remains thus in engagement, acting as a support and bearing as long as the shaft is retained in its rotary displaced condition. The side-switch now being in third position and the line-wipers being in engagement 105 with the first terminal of the first level of the line-bank, the subscriber's line is extended to the line-wipers and thence by way of a trunk-line, similar to the trunk-line leading from the tenth terminal of the first level 110 of the line-bank (the conductors 482, 483 and 519 of which are shown), to an idle 115 "connector." However, the rotation of the shaft is not always terminated when the line-wipers engage with the first set of contacts. For instance, should there be at one time nine "first-selectors" each one using one of the first nine trunks of the first level of banks in multiple with the bank 104, there would then be a guarding potential at 120 each one of the first nine private-bank-contacts of the first row, for reasons similar to those described in connection with the "first-selector" C, when the side-switch of the latter passed into the third position, since 125 the side-switch-wiper 152 became engaged with the grounded contact-point 202.

Assuming the first nine contracts of the first level of the same group to be connected to ground, then when the calling subscriber 130

grounds the rotary side of the line by pressing the rotary-button 35 the side-switch trips into second position. It can be shown that because the first nine private-terminals are supplied with a guarding potential rotation 5 of the shaft will continue until the wipers reach the first idle contact, in this case the tenth. It will be remembered that the circuit through the rotary-magnet is closed when the side-switch-wiper 151 engages with the contact-point 197. At once the rotary-armature is attracted by the rotary-magnet 179 and the shaft is rotated one step. The shaft-wipers are thus moved into engagement with the first contact of the first level 10 of their respective banks, and the private-armature is depressed by the rotary-armature-finger, and at the same time the interrupter-springs 184 and 185 are separated by the interrupter-finger 183. The first private-bank-contact with which the private-wiper engages at the first step being connected to ground, as explained, the private-magnet becomes energized. This energizing circuit 15 extends from the grounded terminal of the battery B through the private-wiper of the switch that is occupying the first trunk of the first level and through the bank multiplying conductors to the contact-point with which the private-wiper 103 is engaged, 20 thence through the private-wiper 103, conductor 479, the winding of the back-release-relay 191, conductor 480, side-switch-wiper 152, contact point 198, conductors 481 and 474, private-magnet 160, conductors 475, 464 and 459, to the non-grounded terminal of battery B and to ground G. The private-armature is thereby retained depressed, even after the rotary-finger returns to its normal 25 position in response to the retracting tension of the rotary-armature retracting-spring 190. Then as soon as the interrupter-springs reengage the circuit through the rotary-magnet is once more closed and the shaft is rotated one more step by the re-energization of the said rotary-magnet 179. The private-wiper, of course, is driven into engagement with the second contact of the first level of the private-bank, and the line-wipers 30 into engagement with the second set of terminals of the line-bank; but still the private-wiper meets another point with guarding potential which causes the private-magnet to retain the private-armature attracted, even while the rotary-armature returns to normal, thus retaining the side-switch in its second position. Thus for a second time the interrupter-springs 184 and 185 are separated by the interrupter-finger, 35 as the rotary-armature is attracted, and then as the rotary-armature 182 returns to its normal position once more the interrupter-springs close together. Clearly, then, the shaft will be rotated in a step-by-step manner as long as the private-wiper continues to

meet the grounded private-bank-contacts. After having been rotated onto the ninth contact the private-wiper is rotated one more step into engagement with the tenth contact of the first level; but, this last contact being 40 without guarding potential, as soon as said private-wiper leaves the ninth contact, the magnetizing circuit of the private-magnet that has up to this time held the side-switch in the second position is then broken. This occurs at just about the point when the rotary-armature is at the end of its attractive stroke. This being true the private-armature does not at once return to its normal position, but follows up the rotary-armature-finger 186 as the latter returns to its normal position. At a given point the escapement-finger which has, during its operation, been resting against the foremost tooth of the upper escapement-spring, leaves 45 said tooth, and the side-switch as a whole is brought to the third position by the side-switch retracting-spring 215, before the interrupter-springs re-engage. The side-switch being in its third position, the subscriber's line which was originally extended only as far as the "first-selector" side-switch-wipers 153 and 154, before the side-switch sprang into its third position, is now 50 extended to the line-wipers 101 and 102. 49 The shaft having been raised one step vertically and rotated ten points the subscriber's line is not only extended to the said wipers but through the rotary and vertical contacts of the tenth terminal of the first level to the 55 trunk-conductors 482 and 483, and to the "connector" D, as shown in Fig. 1. 54 From the description that has preceded, it should be clear that the first ground impulse to the rotary line starts the selector 60 rotating, which rotation may continue automatically until a connection is established with an idle trunk. It will be understood, also, that if while the rotation of the shaft is taking place the subscriber should decide 65 to check the progress of his call he may restore the "first-selector" by returning his receiver to its hook. As a result, the rotary and vertical line-conductors, in a familiar manner, are grounded. Since the side 70 switch is, however, in second position, and as the vertical line conductor 454 is therefore open at this time, the grounding of the vertical line conductor need not be considered; but the rotary-line-conductor 465, 75 however, is connected with the vertical-line-relay 119 through the springs 116 and 114, conductor 470, side-switch-wiper 154, contact-point 200 and conductor 455, and, since the private-magnet, while the private-wiper 80 is passing over grounded contacts, is retained magnetized during said rotation, the private-springs 166 and 167 are maintained closed in contact. The switch is released as 85 follows: Grounding the rotary line while 90

the side-switch is in the second position produces a magnetization of the vertical-line-relay while the private-springs 166 and 167 are together, bringing about, as a result 5 previously pointed out, a magnetization of the release-magnet 137. The energizing circuit of the vertical-line-relay extends from ground G¹ at the sub-station to the release-spring 33, over the rotary-line-conductor 465 to the side-switch-wiper 154, through the vertical-line-relay 119, and through the bridge-cut-off-relay-springs 212 and 213 to the non-grounded terminal of battery B and to ground G. Therefore, the releasing 10 of the "first-selector" while the side-switch is in second position—that is, while the rotation of the shaft is taking place—results from the energizing of the vertical-line-relay at the grounding of the rotary-line-conductor. This is a novel feature of my invention and one which is desirable. It has been customary to connect the side-switch contact-points 177 and 199 permanently, and the contact-points 178 and 200 likewise, the 15 vertical-line-relay terminating directly in the first two, and the rotary-line-relay in the last two. Then, while the shaft is rotating, and while the side-switch is in second position, if for any reason the calling subscriber grounds his vertical-line-conductor the "selector" is released before the operation is terminated, since the private-magnet during said rotation maintains the private-springs 166 and 167 in contact. To obviate 20 this difficulty in the "first-selector" the contact-points 177 and 199 are disconnected, and the contacts 178 and 200 as well, and besides an extra conductor 494 connects the contact-point 177 with the contact-point 200 to enable the switch to perform the release 25 in the manner just described. But after the "first-selector" has once operated, and the side-switch is then tripped into third position, none of the line-relays remain longer 30 in connection with the side-switch-wipers 153 and 154, since there is no connection between the adjoining contact-points over which said wipers slide. After the "first-selector-shaft" has been rotated onto the 35 tenth contact, and the side-switch has passed to third position, the calling subscriber's line is extended to the "connector" D over the trunk-conductors 482 and 483 that terminate in said tenth terminal. Then 40 the release or restoration of said "first-selector" is attained by means of the so-called back-release-relay 191. The lines being extended to the "connector," as shown in Fig. 1, when the subscriber again presses 45 the first button twice, for the second digit, he thereby again grounds the vertical-line-conductor twice, and thereby operates the vertical-line-relay 268 of the "connector" twice. This last energizing circuit, beginning 50 with the ground terminal G¹ at the

sub-station #110, extends to the ground post 41, and then passes through the spring 38 and extends over the vertical-line-conductor 454 to the vertical-side-switch-wiper 153 of the "selector" C, thence through the 55 contact-point 203, the conductor 484, and the line-wiper 102, to the trunk-conductor 482, vertical-line-relay 268, conductors 485, 486, 487, 488, 489 and 490 to the non-grounded terminal of battery B and to ground G. 60 When the vertical-line-relay of the "connector" attracts its armature 326, the latter causes the "connector" line-relay-spring 327 to be pressed against the ground spring 328. The vertical-magnet 272 is thereby energized 65 twice in consequence, and the "connector-shaft" 250 is raised two steps. This last energizing circuit may be traced from the ground terminal G⁶, through the springs 328 and 327, the conductor 491, private-springs 309 and 308, conductor 492, side-switch-wiper 288, conductor 493, vertical-magnet 272, conductors 487, 488, 489 and 490, to battery B and to ground G. Of course, at the first movement of the vertical-arm 274, the release-link 278 is disengaged 70 from the double-dog 281 by the L-shaped piece 277. The circular teeth at this point are so raised that as soon as the double-dog is liberated by the removal of said release-link the double-dog retracting-spring rotates the vertical-dog 267 into engagement with one of the circular teeth, so that when the vertical-magnet becomes de-magnetized and permits the vertical-arm to return to its normal 75 position the shaft, instead of dropping to the original position, is held at its first vertical step. By the second impulse the vertical-magnet raises the shaft to the second level where it is again caught by the said 80 vertical-dog. After pressing the vertical-button 36 twice the subscriber again presses the rotary-button 35 once and operates the rotary-line-relay 269 of the "connector" 85 once. This current also comes through the 90 sub-station ground terminal G¹, and by way of the ground post 41 to the rotary-line-conductor 465, thence through the "first-selector-springs" 116 and 114, conductor 470, side-switch-wiper 154, contact-point 204, 95 conductor 495, private-normal-relay 205, conductor 496, rotary-line-wiper 101, rotary-trunk-conductor 483, conductor 497, ringer-relay-springs 324 and 323, conductor 498, rotary-line-relay 269, conductors 486, 487, 488, 100 489 and 490, to the non-grounded terminal of battery B and to ground terminal G. When the rotary-line-relay is thus magnetized once the rotary-line-relay-armature 329 is attracted once, which latter then forces the 105 springs 330 and 328 into contact. This last operation closes a magnetizing circuit through the private-magnet 298. Said circuit may be traced from the ground terminal G⁶ through the springs 328 and 330, con- 110

ductor 499, private-magnet 298, and conductor 490, to the non-grounded terminal of battery B and to ground G. In this way the private-magnet attracts its armature once. The escapement-finger, by the tension of the retracting-spring 292, passes, during the attraction and restoration of the private-armature, from behind the escapement-tooth 305 to its second position in front of said tooth and behind the next tooth 304, but not quite in contact with the latter because the cam-lug 331 rests against the cam 254. The operation here is the same as that described in connection with the movement of the side-switch in the "first-selector" C. The side-switch being thus changed from its first to its second position, the side-switch-wiper 288 is rotated from engagement with the contact-point 332 onto the contact-point 333. Now, when the subscriber presses the vertical-button 36 ten times, instead of the vertical-magnet being energized, the rotary-magnet 293 is actuated. The ten ground pulsations over the vertical-line-conductor energizes the vertical-line-relay ten times. Said relay, upon attracting its armature ten times, presses the spring 327 in contact with the spring 328 again ten times. The rotary-magnet is, in this way, energized ten times, through the circuit that begins with the ground terminal G⁵ and extends, as above, through the springs 328 and 327 to the side-switch-wiper 288, thence since said side-switch-wiper is in the second position through contact-point 333, conductor 500, rotary-magnet 293, conductors 489 and 490 to the non-grounded terminal of battery B and to ground G. The armature 294 of the rotary-magnet is attracted ten times and each time it is attracted the rotary-pawl engages with one of the longitudinal-teeth 256 and rotates the shaft ten steps, one step at a time, in the same way that the "first-selector" rotary-magnet rotated the "first-selector-shaft." At the first rotary step of the shaft, the shaft-rest 266 engages with the circular teeth and catches the shaft when the vertical-dog 267 is drawn out of engagement with said circular teeth at the time that the rotary-dog 282 reaches the crest of the longitudinal tooth over which it has to pass.

Of course, it will be understood that by the time the rotary-armature strikes the pole-pieces the said rotary-dog drops into locking engagement with the longitudinal teeth and provides a means by which the forward rotary action of the shaft is retained. At the same time that the circular teeth pass into engagement with the shaft-support 266, the shaft-wipers move onto the first contact of the second level of their respective banks. At the second step said wipers are moved onto the second contact of the same level, and so on, step-by-step, until they reach the tenth contact. The

circuit through the rotary-magnet is not interrupted by any automatic device like the circuit of the rotary-magnet of the "first-selector," but each energizing impulse through said magnet is produced and 70 broken directly by the action of the subscriber, just as the vertical-magnet is energized. The last step of the calling subscriber in completing his connection is to again ground the rotary-line-conductor once 75 by pressing the rotary-button 35 once; and again the rotary-line-relay is energized, and again the private-magnet 298 impulsively attracts its armature once. The shaft having been rotated, and the cam 254 having 80 passed out of the way of the cam-lug 331, the side-switch, finding no upper front escapement-tooth, such as the side-switch of the "first-selector" encounters, passes into the third position at the depression of the 85 private-armature. In the third position, of course, the side-switch-arm rests against the side-switch-stop 334, while the side-switch-wipers 288, 289, 290 and 291 pass into engagement respectively with the contact-points 326, 325, 336 and 337. The line-wipers having been rotated onto the tenth set of contacts of the second level of the bank 259, which set constitutes the terminal 90 of the normal-conductors 501 and 502, and, therefore, of the sub-station #120, are thus put in electrical connection with the desired line. The vertical-line-wiper is connected with the vertical-trunk-conductor 482 by the conductor 503, and through the ringer-relay-springs 318 and 317, conductor 504 and the condenser 270; and the rotary-line-wiper 251 is connected with the rotary-trunk-conductor 483 through the conductor 505, ringer-relay-springs 321 and 320, conductor 506 and condenser 271. At the instant that the side-switch-wiper 289 comes into engagement with the grounded contact 325 a guarding potential is put on the tenth contact of the second level of the private-bank, which 100 contact corresponds with the line-terminal of the called sub-station #120. No other "connector" may then venture on the said line. Furthermore, this guarding potential energizes the bridge-cut-off-relay 418 of the "first-selector" E, which relay, by its armature, controls the bridge-cut-off-relay-springs 407, 408 and 409. The magnetizing current which passes through this relay comes from the grounded terminal of battery B to ground G¹⁰ at the connector side switch, to the side switch contact-point 325, side switch wiper 289, and to the private wiper 253, thence through the private-normal-conductor 507 through the private-normal-relay-springs 414 and 413, conductor 508, side-switch-wiper 416, conductor 509, bridge-cut-off-relay 418, to the non-grounded terminal of the battery B and to ground G. The object of energizing said relay is to 110 115 120 125 130

force apart the said springs for the purpose of removing the non-grounded terminal of the battery B from connection with the vertical-line-relay 401 of the called "first-selector." The connection between these two lines having been established the calling party is now ready to signal the sub-station #120.

If for any reason the called line had been 10 busy—for instance, if any of the sub-stations on the line, as sub-station #220, had been using the "first-selector" E, or had any other "connector" been in connection with the said line—there would have been a guarding potential 15 at the tenth private-contact of the second level of the private-bank, said contact corresponding to the trunk-line that leads from the tenth terminal of the second level of the line-bank. Were the said line busy 20 by reason of the "first-selector" E being thus in use, the said private-contact and, of course, all other contacts in multiple with it would then be connected to ground at the instant that the side-switch of said "first- 25 selector" passed into third position. The circuit extends from the said private-bank-contact over the conductor 507, through the private-normal-relay-springs 414 and 413, conductor 508, side-switch 416, to the 30 grounded terminal G^a. In the other case, had some "connector" called the line in question, the said calling "connector", by means of a side-switch-wiper similar to the side-switch-wiper 289, when said side-switch- 35 wiper is in third position, would connect the private-wiper and, therefore, the private-contact in question with a source of guarding potential. Suffice it to say, however, that had there been such a guarding 40 potential at the tenth contact of the second level at the instant that the calling subscriber pressed his rotary-button for the last time, to cause a switching operation corresponding to the digit 0, the "connector" D would 45 have been released and the calling subscriber would have failed to make the desired connection; for the releasing of the "connector" would have resulted from the energization 50 of the "connector" release-magnet 313, the side-switch being, of course, in the second position, which is the position in which the side-switch should be before the rotary-line-conductor is grounded for the last time. The conducting circuit over which the said 55 releasing magnet is energized extends from the ground terminal of the battery B through paths already described to the tenth contact of the second level of the "connector" private-bank, thence through the private- 60 wiper 253, side-switch-wiper 289, contact-point 335, conductor 510, private-springs 310 and 311, conductors 511 and 512, release-magnet 313, to the non-grounded terminal of battery B and to ground G. Of course, 65 when the rotary line is grounded by the

calling subscriber, the private-armature is attracted by the private-magnet over circuits previously pointed out, so that the private-springs 310 and 311 are pressed in contact. The "connector" release-magnet being energized, 70 the release-magnet moves the double-dog 281 in such a manner that the lug 280 on said double-dog is caught and held in the opening 279 on the end of the release-link 278. When the double-dog is thus rotated 75 the locking-dogs 267 and 282 are withdrawn from the shaft, which latter is then free to drop to its normal or released position, in the same manner and for the same reasons described in connection with the "first-selector-shaft". The calling subscriber, thinking he has established connection, presses the signaling-button 16 at his sub-station #110 but with the result that the spring 17 is separated 80 from the contact-point 18 and closed 85 in connection with the contact-point 19. In this way the vertical-line-conductor is connected to ground by way of the ground springs 31 and 30, from the ground terminal G^a, and thence to the contact-point 19 and 90 through the spring 17, secondary circuit springs 22 and 23, contact-point 40, and spring 38, thence to the vertical-line-conductor 454. The "connector" being released, and the side-switch, of course, having been 95 driven by the release-arm 283 back into its first position, about its pivots 345, and with the side-switch-wipers 288, 289, 290 and 291 in engagement respectively with their corresponding contact-points 332, 338, 339 and 100 340, and, of course, with the escapement-finger 312 behind the rearmost lower escapement-tooth 305, the effect of grounding the vertical line is to operate the vertical-line-relay. As above described, the effect of 105 energizing this relay at this time is to raise the shaft of the "connector" vertically, by which motion the normal-arm 263 permits the normal-springs 265 and 264 to come into contact. At this instant a busy signaling current, originating in a suitable device comprising an induction-coil 341, is sent over the line to the calling subscriber's station and through his receiver, said busy signal notifying him that the desired line is busy. 115 The said induction-coil 341 comprises a secondary winding 342 into which the busy signaling current is induced.

When the busy circuit is closed with the calling station #110 the current passes from the coil 342 through the conductor 513 to the contact-point 265; thence by way of the spring 264, conductor 514, contact-point 340, to the side-switch-wiper 291, and thence through the conductor 515, ringer-relay-springs 321 and 320, conductor 506, condenser 271, conductor 483, rotary-line-wiper 101, private-normal-relay 205, conductor 495, side-switch-wiper 154, conductor 470, springs 114 and 116, rotary-line-conductor 120 125 130 135 140 145 150

465, spring 37, contact-point 39, condenser 15, receiver 2, secondary winding 14 of the induction-coil 12, contact-point 18, spring 17, springs 22 and 23, contact-point 40, 70
6 spring 38, vertical-line-conductor 454, side- 75
switch-wiper 153, conductor 484, vertical- 80
wiper 102, vertical-trunk-conductor 482, 85
vertical-line-relay 268, conductors 485, 486, 487, 488 and 489 and back again to the coil 90
10 342. But, as explained, instead of the calling subscriber meeting a guarding potential, he completes his connection in the manner described, and upon proceeding, he presses his signaling-button 16 and thereby grounds 95
15 the vertical-line-conductor by connecting it with the ground terminal G¹ through the springs 30 and 31, contact-point 19, spring 17, and springs 22 and 23, contact-point 40 to the said vertical line. The vertical-line being 100
20 grounded, the "connector" vertical-line-relay is energized, as stated, and its armature causes the springs 327 and 328 to be pressed into engagement. The side-switch-wiper 288 being in connection with the contact- 105
25 point 326, in the third position, the union of said springs energizes the ringer-relay 315. The current flows from the ground terminal G⁶ and through the springs 328 and 327 to the side-switch-wiper 288, thence through 110
30 the contact-point 326 to the ringer-relay 315, to the non-grounded terminal of battery B and to ground G. When the ringer-relay separates the springs 318 and 321 from all connection, and then presses them into 115
35 contact, respectively, with the springs 319 and 322, the ringer-generator H is bridged directly across the line-wipers 251 and 252, and, therefore, across the line of the called subscriber, with the result that the ringer 120
40 at the sub-station #120 is energized. This particular generator under the control of the "connector" D produces a current of such frequency that only the bells at the said sub-station will resound. If the sub- 125
45 station #220 had been called a different "connector" would have been reached by the action of the "first-selector," which "connector" would have been one of a group of "connectors" provided with a 130
50 ringer-generator the frequency of the current of which is capable only of ringing stations provided with ringers that respond only to said current. The path followed by the current that originates in the ringer- 135
55 generator H passes from the brush 343 to the spring 322, thence to the spring 321, and by way of the side-switch-wiper 291 to the conductor 505, and thence to the wiper 251, from which point it passes on to the normal- 140
60 conductor 502, thence to the line-conductor 516, spring 425, contact-point 426, thence through the condenser 427 to the ringer 428, from which latter it passes to the spring 429 and switch-hook 430, contact-point 431, 145
65 spring 432, vertical-line-conductor 517, nor-

tion #120 and passes through the ringing apparatus of sub-station #220; but the ringer at that station being adjusted so that it does not respond to this particular character of current, the subscriber at that station receives no signal. The bell of the first sub-station—station #120—responds readily, and the subscriber there answers by removing his receiver 433 from the hook 430.

As soon as the calling subscriber ceases 30
to press the signaling-button 16 the ringer-relay becomes deenergized and the springs 318 and 321, respectively, reengage with the springs 317 and 320, at which instant the two receivers 2 and 433 of the respective 35
sub-stations #110 and #120 become connected in the same continuous circuit. Said circuit, beginning with the receiver 2, may be traced through the secondary winding 14 of the induction-coil 12, through the contact-point 18 and spring 17, and through the springs 22 and 23 to the vertical-line-conductor 454, thence through the side-switch-wiper 153 of the "first-selector" C, conductor 484 and vertical-line-wiper 102 to the vertical-trunk-conductor 482, thence through the condenser 270, conductor 504, ringer-relay-springs 317 and 318, side-switch-wiper 290, conductor 503, and vertical-line-wiper 252 to the normal-conductor 501. From here it extends to the vertical-line-conductor 517 to the spring 432, and through the contact-point 431, springs 439 and 438, springs 437 and 436, secondary winding 434 of the induction-coil 435, receiver 433, contact-point 426, spring 425 to the rotary-line-conductor 516, thence over the rotary-normal-conductor 502, rotary-line-wiper 251, conductor 505, side-switch-wiper 291, ringer-relay-springs 321 and 320, 100

is established part of the feature of my improved system will come prominently into use if the subscriber at sub-station #210 attempts to make a call. I have found in 5 practice that if two party-lines similar to the ones represented in Fig. 1 are connected by means of switching devices of the character to which my improvement applies—that if after the said connection is established 10 any one of the remaining substations on either line, by attempting to make a call grounds either or both of his line-conductors, the established connections will be broken by the releasing of the switches employed 15 in making the connection. It is for the purpose of preventing such interference that I have provided a non-interfering device, such as the one at substation #210, comprising the lock-out magnet 600. The connection 20 already described being established, if a subscriber at that station—station #210—removes his receiver from its hook, said lock-out magnet will be operated so as to prevent a connection between the ground 25 post 601 or the signaling-button-contact 602 or the ground release-spring 603 and ground terminal G'. The switch-hook-springs are so adjusted that the springs 604 and 605 which are normally disengaged when the 30 switch-hook is down, as indicated at substation #220, are thrown into contact as the switch-hook rises, before the spring 606 is separated from the spring 607. Since the "first-selector" is off-normal the rotary-line- 35 conductor 465, which is normally disconnected from the non-grounded terminal of the battery B, is then connected with said battery through either one of several circuits, depending upon the position of the side- 40 switch-wiper 154 of the "first-selector" C, since the rotary-line-normal-springs 114 and 116 are then in contact. Therefore, there is an instant, when the switch-hook is rising, in which a circuit through the lock-out relay 45 600 is completed, through which circuit a current flows that will operatively magnetize said relay. This circuit, when the "first-selector" side-switch is in the third position, and, therefore, when the subscriber's line is extended to the "connector," 50 extends from ground G' through the springs 606 and 607 to the lock-out relay 600, thence through the springs 604 and 605, contact-point 608, spring 609, through the rotary-line-conductor 465, and thence through the 55 springs 116 and 114, side-switch-wiper 154, conductor 495, normal-relay 205, conductor 496, rotary-line-wiper 101, rotary-trunk-conductor 483, conductor 497, ringer-relay- 60 springs 324 and 323, conductor 498, "connector" rotary-line-relay 269 to the non-grounded terminal of battery B and to ground G. The energization of this lock-out relay does not take place however until 65 the switch-hook has risen sufficiently to draw

the lock-controlling rod 610 out of reach of the lock piece 611.

At the instant that the relay 600 is magnetized the armature 612 is attracted by the pole-piece of the relay, which armature, as 70 it strikes the pole-piece, clears the lock piece 611. The latter is forced up in front of said armature in such a manner that the armature is locked against the pole-piece and retained there even after the energizing current ceases to flow through the locking magnet. Said armature, being depressed, causes the spring 613 to be separated from the spring 614 and thereby interrupts the continuity of the grounding connection from 75 the ground post 601, or the ground contact-point 602, or the release spring 603, to the ground terminal G', even after the ground springs 615 and 616 are permitted to close. Therefore, the subscriber at the sub-station 80 #210 may work his calling device or press his signaling-button or hang up his receiver without interfering with the connection existing at the time. It is not necessary for the side-switch-wiper 154 to pass into 85 the third position, while the rotary line off-normal springs 116 and 114 are closed in contact, in order that the lock-out magnet of the substation #210 may be energized, should the subscriber at that station 90 attempt a call. If the side-switch happens to be in the first position when the attempted call is made, the energizing circuit, instead of passing from the side-switch-wiper 154 to the conductor 495, and thence through 95 the private-normal-relay 205 to the "connector," passes to the contact-point 178 and thence through the rotary-line-relay 120 of the "first-selector" and bridge-cut-off-relay- 100 springs 211, 212 and 213 to the non-grounded terminal of the battery B. If the attempted call occurs while the side-switch is in second position the energizing circuit, after reaching the side-switch-wiper 154, takes still another path which includes the 105 contact-point 200, the conductor 494, the vertical-line-relay 119, bridge-cut-off-relay- 110 springs 212 and 213 to the non-grounded terminal of the battery B and to ground G. If the subscriber does hang up his receiver before the subscriber at sub-station 115 #110 destroys his connection with the subscriber #120 the switch-hook 617, upon passing to its normal position, again separates the springs 604 and 605, thus opening 120 the energizing circuit through the lock-out magnet 600. Immediately after said springs are opened, the locking-rod 610 then drives the locking piece 611 out of the way of the locking magnet-armature 612, and the said 125 armature then returns to its normal position, restoring the connection between the springs 613 and 614. Since the receiver 618, while the switch-hook is up, is bridged across the line-conductors 465 and 454, the subscriber 130

at that station will, therefore, be able to listen-in on the line and learn that his line is busy, and thus know the reason for not obtaining the connection he desires. In my 5 improved "connector" all relays have been removed from across the line between the condensers and the line-wipers; also, since the bridge-cut-off-relay 418 of the called "first-selector" is energized, and since the 10 connection between the line-relays 401 and 402 and the non-grounded terminal to battery has been thus interrupted at the spring 409, the subscriber at sub-station #220 on the called line may momentarily ground 15 either or both of the line-conductors without interfering with the connection established. Therefore, the calling line is rendered non-interfering by the use of a lock-out device comprising a lock-out magnet, 20 such as the lock-out magnet 20, while the called line is rendered non-interfering by the removal of all connections to main battery as far as the condensers and, therefore, of all operative relays from across the main conductors, by the energization of the bridge-cut-off-relay 418, at the instant that the calling "connector" completes its connection with the called line, as previously described. The conversation having been terminated, 25 the subscriber at the calling sub-station may release the connection with the line leading to the substation #120, at any instant, by simply restoring his receiver to its hook. The grounding of the rotary and vertical 30 line-conductors 454 and 465 following as a result, the rotary and vertical line-relays of the "connector" then become magnetized in the well-known manner.

Among the line-relay-springs the two 40 longest of these springs, 344 and 345, are peculiarly adjusted. If either relay is energized alone, the ends of these springs do not come into contact; but if both relays are magnetized at once, the ends are then 45 brought near enough to make electrical connection. The engagement of these two springs closes a circuit that includes the release-magnet 313 of the "connector" and the back-release-relay 191 of the "first-selector" in 50 series. The ground point of this circuit is found at G⁴ at the "first-selector" side-switch. The current entering the circuit at said point from ground passes to the contact-point 202, and thence to the side-switch-wiper 152, after which it passes through the conductor 480 to the back-release-relay 191; then it flows through the conductor 479, 55 private-wiper 103, over private-trunk conductor 519, and through the release-springs 344 and 345 at the "connector" D, thence over the conductors 520 and 512 and through the release-magnet 313 to the non-grounded terminal of battery B and to ground G. Therefore, both the back-release-relay of the

"first-selector" and the release-magnet of 65 the "connector" are energized simultaneously. The result of energizing the release-magnet of the "connector" is well known—that is, the "connector-switch" is restored to its normal position by the release-armature 314, 70 which latter then, by engaging the double-dog at a point between the bearings 335 and the lug 280, is driven beneath the release-link 278, by which latter it is then caught and locked, and as it is thus moved the release-arm 283 drives the side-switch to its normal position by means of the side-switch-link 285. When the back-release-relay of the "first-selector" attracts its armature, it closes a connection between the back-release-relay-springs 192 and 193, and thereby closes 80 an energizing circuit through the release-magnet 137 from the ground terminal G⁸ through the said back-release-relay-springs 193 and 192, the release-magnet 137, to the 85 non-grounded terminal of battery B and to ground G. As a result, the "first-selector" is also released when the double-dog is caught and drawn by the release-link 135 to its normal position, by which operation the 90 locking dogs 143 and 144 are withdrawn from the shaft and the side-switch restored to its first position by means of the releasing arm 145 and the side-switch-link 149. At the instant that the "connector" private-wiper breaks connection with the tenth contact of the second level of the private-bank 260, when the shaft begins to return to its 95 normal position, the circuit through the bridge-cut-off-relay 418 of the called "first-selector" is broken, and becoming deenergized restores the original connection between the rotary and vertical line-relays of the called "first-selector" and the non-grounded terminal of battery B. The release being completed, and the called subscriber having restored his receiver also, any one of the subscribers on either of these two lines is then at liberty to use the line. If, 100 when the subscriber at the sub-station #210 locked himself out of service by raising his receiver, the subscriber at sub-station #110 had restored the switches by hanging up his receiver at the instant that the shaft of the "first-selector" C falls, and separated the 105 springs 116 and 114, the circuit through the lock-out magnet 600, of course, would be broken; but the subscriber at the sub-station #210 cannot use his telephone until he has first depressed his hook and afforded the 110 lock-out magnet-armature 612 an opportunity to regain its normal position. Since it is very important, while a party-line is not in use, that the rotary-line-conductor be disconnected from the main battery, special 115 means have been provided, in connection with the "first-selectors" whereby a light signal may be maintained if the shaft of 120

any "first-selector" by any accident is raised off-normal and retained so indefinitely.

It is evident that so long as the shaft of the "first-selector" of a line is raised none 5 of the sub-stations on the line are able to make a call, since the raising of a switch-hook while the rotary-line-conductor is closed renders the particular sub-station inoperative, owing to the provision of the 10 lock-out device. The means thus provided comprises a lamp 214 one of the terminals of which is connected to ground at the ground-point G⁴, the other terminal of said lamp being connected with the off-normal spring 15 117 which, when the shaft is off-normal, closes connection with a corresponding off-normal spring 115, the latter, when the side-switch-wiper 151 is in first position, being connected with the non-grounded terminal 20 of battery B through the rotary-magnet 179. By these means, each time the shaft is raised, and as long as the side-switch of the "first-selector" is in its first position, the lamp 214 remains lighted. Of course, as soon as the 25 side-switch-wiper 151 passes into the second position the connection to main battery through the magnet is interrupted and the light goes out again; but if the shaft is simply raised and retained so the light will continue lighted and will thereby attract the attention of the switchboard attendant in charge of the switches.

So far, the features of my invention have come into use only when one party-line has 35 called a second party-line; but my improved system also provides means whereby a subscriber on one party-line may call another subscriber on the same line. The manner in which such a connection is accomplished will 40 become apparent from the following. In Fig. 6 the sub-station #310 is shown calling the sub-station #110 on the same line, while the sub-station #210, also on the same line, is shown locked out by an attempt of a subscriber at that station to make a call. In the usual manner, the subscriber at the sub-station #310, in order to call the subscriber #110, presses the vertical-button 625 once, and the rotary-button 626 once, then again 45 the vertical-button once, and the rotary-button once, and for the last time the vertical-button ten times and the rotary-button once. When the vertical-line-conductor 454 is grounded once the "first-selector-shaft" 100 50 is raised to the first level, and when the rotary-line-conductor 465 is grounded once the usual rotation of the shaft ensues which, if the first nine trunks of the first level are busy, will cause the shaft to rotate the wipers 55 onto the tenth terminal of the first level, with the private-wiper 103 in contact with the private-trunk-conductor 519. The "first-selector" having connected the line with the "connector" D, it is evident that when the

vertical-line-conductor 454 is grounded once 65 the vertical-line-relay 268 is energized once, and in the well-known manner the "connector-shaft" 250 is raised one step. Upon the grounding of the rotary line, the rotary-line-relay 269 of the "connector" is energized, 70 and as a result the private-magnet 298 is energized, and as a final result the side-switch is tripped into second position. With the side-switch thus changed, when the vertical-line-conductor is next grounded ten 75 times the vertical-line-relay is energized ten times, which in turn causes the rotary-magnet 293 to rotate the shaft onto the tenth terminal of the first level of the "connector-banks." At the next step, and the last to 80 follow, the rotary-line is grounded for the last time. It is evident that the process of calling the subscriber #110 consists in causing the line across which said sub-stations are located to call back upon itself, so to 85 speak, through the "first-selector" C, and by means of the "connector" D; therefore, in such case the "connector" calls a busy line. The side-switch of the "first-selector" C being in the third position, a guarding 90 potential exists at the tenth private-bank-contact of the first level of the "connector-bank" 260. This guarding potential is communicated to said point from the ground terminal G⁴ of the "first-selector," to the 95 contact-point 202, through the side-switch-wiper 152, private-normal-springs 208 and 207, private-normal-conductor 196, to the contact-point in question and to all other contact-points connected therewith in multiple. Then, from the explanations which have preceded, it would be natural to expect the "connector" to be released at the last grounding of the rotary line; but special provision has been made whereby, when necessary, a line may call back upon itself, 105 although no other line is able to call this line while the latter is busy.

Attention is called to the fact that the guarding potential at the "connector" private-bank 110 is communicated to said point through the private-normal-relay-springs 208 and 207; also that after the "first-selector" connects with the "connector" each time that the rotary line is grounded the private-normal-relay 205 is magnetized in unison with the rotary-line-relay 269 of the "connector." With such construction, it is evident that at the instant the rotary line is grounded, and at the same time that the rotary-line-relay 115 of the "connector" is energized, the guarding potential at the private-bank-contact in question is removed as soon as the armature of the private-normal-relay is attracted. Clearly, then, the "connector" will not be released when the private-magnet presses the private-springs 310 and 311 into contact, 120 since for the time being the ground or 125

guarding potential that produces a busy release of the "connector" is absent. The grounding of the rotary line, therefore, energizes the private-normal-relay 205 at the 5 "first-selector," and the rotary-line-relay 269 of the "connector." The former removes the ground connection from the private-bank of the "connector," and the latter causes the private-magnet 298 to be energized, and thereby causes the side-switch to pass from the second to the third position when the armature of the private-magnet is attracted. As soon as the side-switch passes into the third position the private-wiper 15 253 is grounded through the side-switch-wiper 289, from the point G^{10} , and the extended line-conductors 482 and 483 are connected through the side-switch-wipers 290 and 291, and through the vertical and rotary line-wipers 252 and 251, to the vertical and rotary normal-conductors 194 and 195 and, therefore, to the vertical and rotary line-conductors 454 and 465. As soon as the ground is cut off from the rotary line, 20 25 the private-normal-relay then returns to its normal position, as well as the rotary-line-relay of the "connector." The former then permits the reengagement of the springs 207 and 208, while the restoration of the latter 30 permits the restoration of the private-magnet, which breaks the contacts between the private-springs 310 and 311. Having completed the calling operation the calling subscriber presses the signaling-button 627 and 35 thereby grounds the vertical-line-conductor in the usual manner. The circuit, of course, extends from the ground terminal G^{11} at the substation #310, to the contact-point 628 and through the spring 625 to the vertical-line-conductor and thence by way of the "first-selector" to the vertical-line-relay of the "connector" to the non-grounded terminal of the battery B. The side-switch-wiper 288 being in connection with the contact-point 326, the energization of the vertical-line-relay energizes the ringer-relay over a circuit that has already been pointed out. As a result, the terminals of the ringer-generator H are brought in across the vertical 40 and rotary line-wipers 252 and 251, and, therefore, across the normal-conductors 194 and 195. The ringer current is thus supplied to the rotary and vertical line-conductors 465 and 454, and thence through the 45 ringing apparatus at sub-stations #110 and #210, the switch-hooks at these stations being in normal position. However, since only the ringer at the sub-station #110 is able to respond to the ringer current produced by 50 the ringer-generator H, only the sub-station #110, is signaled. The path of the ringing current extends from the ringer-generator-brush 343 through the ringer-relay-springs 322 and 321, side-switch-wiper 291, conductor

55 505, rotary-wiper 251, normal-conductor 195, rotary-line-conductor 465, condenser 15, ringer 11, ringer-spring 21, switch-hook 3, to the vertical-line-conductor 454, vertical-normal-conductor 194, vertical-wiper 252, conductor 503, side-switch-wiper 290, ringer 70 70 relay-springs 318 and 319, and back to the generator-brush 344. The subscriber at substation #110, upon removing his receiver, connects the latter across the rotary and vertical line-conductors, and in series with the 75 receiver at the sub-station #310, by circuits that are familiar.

It will be understood, of course, that when the called subscriber #110 removes his receiver he energizes and locks his relay 20, 80 as shown, with the same result already described in connection with the substation #210; but this, of course, does not affect the talking circuit in the least. It will be evident, therefore, that the only subscriber 85 who can release the established connection is the calling subscriber.

It will be noticed that the ringer-relay is provided with two extra springs 323 and 324 which are in series with the rotary-line-relay 90 269 of the "connector" between the conductor 483 and said relay. The object in providing these springs is to prevent the rotary and vertical line-relay of the "connector" from becoming energized by the ringing 95 current when said current is applied to the rotary and vertical normal-conductors 195 and 194. Should these two relays become energized simultaneously, the switches would, of course, be released in a well-known 100 manner. The path taken by the current would be from the rotary-normal-conductor 195 through the side-switch-wiper 154, conductor 495, private-normal-relay 205, wiper 101, trunk-conductor 483, conductor 497, 105 ringing-relay-springs 324 and 323, conductor 498, rotary-line-relay 269, conductor 485, vertical-line-relay 268, vertical-trunk-conductor 482, wiper 102, conductor 484, side-switch-wiper 153, to the vertical-normal-conductor 194. These two subscribers being 110 connected, should the subscriber at sub-station #210 attempt to make a call, and since the rotary-line-conductor is connected to main battery through the rotary-line-relay 115 of the "connector," in a well-known manner, the lock-out magnet 600 at the sub-station #210 becomes energized, and the sub-station is locked out by the armature 612 of the lock-out magnet separating the ground circuit-springs 613 and 614, with the usual result. After the two subscribers have communicated, and if the subscriber at the sub-station #310 should wish to disconnect the 120 switches, he will restore his receiver to the 125 switch-hook and thus ground the rotary and vertical line-conductors at the release-springs 619 and 620, by the grounded spring

621. The result of grounding the two line-conductors, of course, would be that the rotary and vertical line-relays 268 and 269 of the "connector" would be simultaneously magnetized, in the well-known manner, and over circuits which are already familiar. The release-springs 344 and 345, under the control of these line-relays, being brought in contact, the back-release-relay of the "first-selector" and the release-magnet for the "connector" will become magnetized at the same time, producing the release or restoration of these two switches. It is evident that if one subscriber on one line has signaled another subscriber on the same line the calling subscriber may release the switches and then by raising his receiver again may still continue to communicate with the subscriber he has signaled, inasmuch as all of the 15 sub-stations on the same line are bridged directly across the line-conductors. Among the features that are necessary to the successful operation of my improved non-interfering party-line telephone system, as disclosed in the foregoing, is a lock-out magnet at each sub-station, by means of which one subscriber on a given line, when he wishes to use said line, may monopolize the use of the line in question, either to call a second line or to call another subscriber on the same line. Then, if a second subscriber on the same line attempts to make a call after the first subscriber has operated the "first-selector," the lock-out device at the said second 20 subscriber's station, or even at a third subscriber's station, and so on, is operated in a manner to render useless the ground circuit at the interfering station. Furthermore, the "first-selector" is provided with a normally-open rotary-line-conductor which terminates in one of the two springs that are normally in non-engagement and which only close contact after the shaft of the "first-selector" has been operated vertically. All "first-selectors" are provided with a bridge-cut-off-relay that comes into use when a circuit is completed between two lines, comprising a calling "first-selector" and called "first-selector" and an intermediate connecting "connector." The purpose of said bridge-cut-off-relay is to disconnect the line-relays of the called "first-selector" from the non-grounded terminal of the battery, so that when the calling and called subscribers are communicating a second subscriber on the called line may not be able to interfere with the established connection, for this he would do were not the line-relays disconnected from the battery, as stated. When operating his calling device the said second subscriber would ground the vertical and rotary line-conductors in the usual manner, and thus would bring about undesirable complications. In addition, the "first-selector" is provided

with a private-normal-relay which enables a 65 "connector" to complete the connection without being released over the busy release circuit.

It will be noted that the circuit through the signaling lamp that gives notice if by accident a "first-selector-shaft" is raised off-normal vertically, comprises the rotary-magnet; but the current that the lamp allows to pass is too weak to operate the armature of the said rotary-magnet. Special circuits are provided by which the rotary-line-conductor is at all times maintained in connection with the non-grounded terminal of the battery after the shaft is raised irrespective of whether the side-switch is in the first, second or third position. When the "first-selector" side-switch is in the first position this circuit comprises the rotary-line-relay of the said "selector"; with the side-switch in the second position it comprises the vertical-line-relay instead; but when the side-switch is in the third position, and after the "first-selector" is connected with the "connector", said circuit comprises the private-normal-relay and rotary-line-wipers of the "first-selector" in series with two extra ringer-relay-springs and the rotary-line-relay of the "connector". The "connector" is deprived of all operating magnets or relays between the condenser of the rotary-line-conductor and the side-switch-wiper, which latter is normally connected with said condenser. When one subscriber has connected with another party-line the improvements in the called "first-selector" and "connector" make it impossible for a second party on the called line to interfere with the temporarily established circuits. The rotary-normal-conductor leading from each "first-selector" is connected to the rotary-line-conductor at a point between the sub-station and the spring that constitutes the normal terminal of the rotary-line-conductor; and thus it will be seen that normal connection between the rotary-normal-conductor and the rotary-line-side-switch-wiper is open. The "connector" is also provided with a tooth escapement which has two teeth on the lower side and one tooth on the upper side, thus enabling the "connector" side-switch to spring from second to third position while the private-magnet is magnetized. The ringer-relay is provided with two additional springs that are separated when the calling subscriber presses his signaling-button, in order that the ringing current which a "connector" sends back onto the line of the calling "first-selector" may not energize the line-relays of said "connector" and thereby release it. It will be understood that when the "first-selectors" of the system are raised to the first level they connect with "con-

nectors" that control ringer-generators producing an alternating current of a particular character; then, when the "first-selectors" are raised to the second level, "connectors" are reached which have control of ringer-generators producing current of different character, while from the third level the "first-selectors" connect with "connectors" using still other ringing currents, 5 and so on. In this way the level to which the "first-selector-shaft" is raised in making a call will determine the particular sub-station on a given line that may be signaled. The system under consideration 10 comprises, as stated, any suitable scheme for selectively signaling. The lock-out relays at the sub-stations have been found to give good results when wound to a resistance of about 2100 ohms, but other resistances may 15 be used if desired. The energizing circuits in which such relays take part have been shown to comprise in each case some other relay in series; but the amount of current that flows when the lock-out relay is in series with some of the other of said relays is 20 too small to permit any other but the lock-out relay to be energized.

Thus it will be seen that any subscriber can call his own line, so to speak—that is, 30 any subscriber on a party-line—inasmuch as the "connector" used in such case will not be automatically released as soon as it engages the multiple line-terminal connected with the line from which the call came. 35 Furthermore, if one subscriber is using the party-line, no other subscriber on the same line can use the line for either switching or signaling purposes. In other words, the two subscribers who are conversing over the 40 line are safe against intrusion or molestation to this extent, namely, that no other subscriber can use the line for either switching or signaling purposes, nor can any other subscriber on the same line so operate his 45 telephone or switching devices as to endanger the continuity of the circuit established between the two subscribers who are talking. It is always an undesirable thing, of course, to have it possible for one subscriber 50 on a line to listen-in and hear the conversation conducted over the line by some other subscribers; but in an automatic or semi-automatic telephone system I deem it of far greater importance to provide against the 55 breaking by a third subscriber of a circuit already established between two other subscribers; for while such listening-in may be a source of more or less annoyance, it is evident that this is not so important a consideration as is the maintenance of the continuity of any established talking circuit. 60 In other words, in a party-line automatic or semi-automatic telephone system, of the character herein described, it will be impossible 65 to give satisfactory telephone service

to party-line subscribers who find that they cannot use the line without danger of having another subscriber come in and practically take the line away from the one already in possession of it. Subscribers may 70 tolerate listening-in, objectionable though it is; but the situation in which a party-line subscriber could not use the line without a guarantee against interference on the part of the other subscribers on the line would be 75 intolerable. It is evident, however, that my improved lock-out magnet or relay devices are of a character to prevent a subscriber from transmitting any signals and from 80 accomplishing the closure of any circuits at the exchange or central station. In this respect, therefore, and broadly considered, my improved lock-out arrangement is fully as applicable to manual board telephone exchanges as it is to automatic or semi-automatic exchanges. 85

From the foregoing it will be seen that my present invention is in the nature of an improvement on the party-line telephone system described and claimed in my prior application No. 270,591, filed July 20, 1905. 90

It will be understood that the subscribers' bells described in connection with my present invention may be tuned in any suitable manner, so that they may selectively respond 95 to the different kinds of ringing current, as, for example, alternating currents of different frequencies.

From the foregoing it will be seen that I provide a non-interfering automatic party-line telephone exchange system in which provision is made for preventing one subscriber on a party-line from interfering with a connection previously established over said line by another subscriber on the 100 same line. In other words, automatic switching machinery is provided and combined with means by which each subscriber on a party-line is prevented from disturbing the said automatic switching means whenever the same is already in use by another subscriber on the same line. Means are provided for preventing the locking out of the first subscriber who calls on the line, in combination with means for then locking 105 out and preventing any other subscriber on the same line from interfering with the use thereof by the subscriber who called first, and who is already in possession of the line 110 for either switching or talking purposes. 115

What I claim as my invention is:—

1. In a telephone system, a subscriber's telephone, a normally-open connection to ground, a relay controlling the continuity of said connection to ground, a hook-switch controlling the energizing of said relay, and automatic switching machinery adapted to be operated by electrical impulses transmitted from the subscriber's station through 125 the medium of said ground connection. 130

2. In a telephone system, the combination of a subscriber's transmitter for sending the electrical impulses representing the called number, a ground connection adapted to operate with said transmitter in sending the said impulses, a relay adapted when energized to open the said connection to ground, and automatic switching machinery adapted to be operated by the said electrical impulses. 5
- 10 3. In a telephone system, the combination of subscriber's line-conductors, a normally-open connection to ground at the subscriber's station, means for closing said ground connection when the subscriber uses his telephone, a relay in said ground connection, another path to ground controlled by said relay, an energizing circuit for said relay including one line-conductor, automatic switching means responsive to the grounding of the line over the path controlled by said relay, and means by which another subscriber controls the energizing of said relay. 15
- 20 4. In a telephone system, the combination of a subscriber's telephone and auxiliary switching devices, a relay associated with said telephone and auxiliary switching devices, grounded switching and ringing circuits controlled by said relay, a subscriber's line, a normally-open grounded energizing circuit for said relay, automatic switching means responsive to the grounding of the line, said energizing circuit including a conductor of said subscriber's line, and means by which another subscriber controls the energizing of said relay. 25
- 30 5. In a telephone system, a subscriber's line, a plurality of subscribers' telephones and auxiliary switches connected with said line, a relay for each subscriber's telephone, ground connections controlled by said relays, signaling circuits including said ground connections, suitable circuits whereby an attempt to use any telephone serves to energize its allotted relay if any other subscriber is already in possession of the line, and automatic switching means responsive to the grounding of the line. 35
- 40 6. In a telephone system, the combination of a line, a plurality of telephones and subscribers' switching devices connected with said line, a relay for each telephone, a normally-closed ground connection to one terminal of the coil of each relay, a normally-open connection extending between the other terminal of each relay-coil and one side of the said line, and automatic switching means responsive to the grounding of the line. 45
- 50 7. In a telephone system, the combination of a line, a plurality of subscribers' telephones and switching devices connected with said line, a relay for each telephone, switching and signaling circuits controlled by said relay, suitable circuits whereby the attempted use of any telephone serves to energize its allotted relay if the line is already 55
- in possession of another subscriber, locking devices for locking the relays in their energized positions, restoring means operative to restore any off-normal-relay to its normal condition when its allotted telephone is hung up, and automatic switching means responsive to the grounding of the line. 60
- 70 8. In a telephone system, the combination of a subscriber's telephone and auxiliary switching devices, a relay allotted to said telephone, controllable by another subscriber, an electrically-propelled and step-by-step-actuated switching machine provided with a line-relay, an energizing circuit including the windings of said relays connected in series, means operated by the energizing of the first-mentioned relay to prevent the subscriber from calling, a plurality of bridges adapted to be placed across the talking circuit while a connection is being established, and means for reducing the number of said bridges when said connection is completed. 75
- 80 9. In a telephone system, the combination of a subscriber's telephone, a relay allotted to said telephone, controllable by another subscriber, a "connector" provided with a line-relay, an energizing circuit including the windings of said relays connected in series, a hook-switch controlling said circuit, a plurality of bridges adapted to be placed across the talking circuit while a connection is being established, and means for reducing the number of said bridges when said connection is completed. 85
- 90 10. In a telephone system, the combination of a subscriber's telephone and auxiliary switching devices, a relay allotted to said telephone, controllable by another subscriber, an electrically-propelled and step-by-step-actuated switching machine provided with a relay, an energizing circuit including the windings of said relays connected in series, a ground connection opened by the first-mentioned relay to prevent the subscriber from calling, a plurality of bridges adapted to be placed across the talking circuit while a connection is being established, and means for reducing the number of said bridges when said connection is completed. 95
- 100 11. In a telephone system, the combination of a subscriber's telephone, a relay associated with said telephone, means controlled by said relay to prevent the subscriber from calling, a "connector" provided with a ringer-relay, a ringing-generator associated with said ringer-relay, and an energizing circuit for said subscriber's relay, said energizing circuit being controlled at one point by the said ringer-relay. 110
- 105 12. In a telephone system, the combination of a subscriber's station, a relay associated with said station, a "first-selector" provided with a rotatable and endwise-shiftable switch-shaft controllable from said station, 115
- 120
- 125 130

an energizing circuit for said relay adapted to be closed by the initial endwise movement of said shaft, and means controlled by said relay for preventing said subscriber's station from controlling said selector.

- 5 13. In a telephone system, the combination of a subscriber's telephone and auxiliary switches, a relay allotted to and associated with said telephone, a subscriber's line, a 10 pair of relays bridged across the line, a battery having its non-grounded pole connected with said relays at a point between them, one side of the line being normally disconnected from one of said line-relays, 15 means for closing connection between this side of the line and its allotted line-relay when the other line-relay is energized, a normally-open energizing circuit for said subscriber's line-relay, said energizing circuit including the side of the line which is 20 normally disconnected from its line-relay, and means controlled by said subscriber's relay for locking out said telephone.

14. In a telephone system, the combination 25 of a subscriber's line, a switch-hook, a relay having normally-closed switch-contacts for controlling a ground-connection, an armature adapted to open said contacts when the relay is energized, a locking device for 30 catching and holding the armature in its attracted position, means for releasing the said armature when the switch-hook is restored to its normal position, and automatic switching means responsive to the grounding 35 of the line.

15. In a telephone system, the combination of a subscriber's line, a switch-hook, a relay having normally-closed switch-contacts, an armature adapted to open said contacts 40 when the relay is energized, a locking device for catching and holding the armature in its attracted position, means for releasing the said armature when the switch-hook is restored to its normal position, a signaling 45 circuit including said contacts, and automatic switching means responsive to the grounding of the line.

16. In a telephone system, the combination 50 of a subscriber's switch-hook, a relay having normally-closed switch-contacts, an armature adapted to open said contacts when the relay is energized, a locking device for catching and holding the armature in its attracted position, means for releasing the said armature when the switch-hook is restored to its normal position, automatic 55 switching machinery, and switch-operating circuits including said contacts.

17. In a telephone system, the combination 60 of a subscriber's line, a switch-hook, a relay associated with said switch-hook controllable by another subscriber and controlling a ground connection, a grounded energizing circuit for said relay, means whereby said circuit is opened when the hook is

raised from its normal position, automatic switching means responsive to the grounding of the line, a plurality of bridges adapted to be placed across the talking circuit while a connection is being established, said 70 bridges containing an electromagnetic device for controlling the establishment of the talking circuit, and means for reducing the number of said bridges when said connection is completed.

- 75 18. In a telephone system, the combination of a subscriber's line, a switch-hook, a relay associated with said switch-hook, switching and signaling circuits controlled by said relay, an energizing circuit for said relay, means whereby said energizing circuit is momentarily closed at one point and then opened at another point by the release of said switch-hook, and automatic switching means responsive to the grounding of the 80 line.

- 85 19. In a telephone system, the combination of automatic switching machinery, subscriber's means for operating said switching machinery, controlling circuits for said 90 switching machinery, a relay at the subscriber's station controllable by another subscriber, said relay being adapted to control the said circuits to render the control of said switching machinery inoperative, a talking circuit excluding the winding of said relay, a plurality of bridges adapted to be placed across the talking circuit while a connection is being established, said bridges containing 95 an electromagnetic device for controlling the establishment of the talking circuit, and means for reducing the number of said bridges when said connection is completed.

- 100 20. In a telephone system, the combination 105 of a subscriber's line, a plurality of subscribers' telephones connected with said line, automatic switching machinery under the control of the subscribers, suitable grounded line circuits for controlling said switching machinery, a relay at each subscriber's station excluded from the path of voice currents and controllable by another subscriber, said relays being adapted to control the said circuits to prevent use of said switches by one subscriber when they are in use by another on the same line, a plurality of bridges adapted to be placed across the talking circuit while a connection is being established, said bridges containing an electromagnetic device for controlling the establishment of 110 the talking circuit, and means for reducing the number of said bridges when said connection is completed.

- 115 21. In a telephone system, a switching machine provided with an operating magnet, a side-switch-wiper and a visual signal, and a normally-open circuit for said signal including said magnet and side-switch-wiper 120 in series.

- 125 22. In a telephone system, a battery, a 130

- “connector” comprising a pair of line-relays permanently connected to one terminal of battery, an energizing circuit for one of said relays, a third relay by a single energization controlling the continuity of said energizing circuit at one point only, and controlling the talking circuit, and switching means controlled by said line relays.
23. In a telephone system, a battery, a “connector” provided with a pair of line-relays permanently connected to one terminal of battery, a ringer-relay for use in ringing different subscribers and provided with normally-closed switch-contacts, and an energizing circuit for one of said line-relays, said energizing circuit including the normally-closed switch-contacts.
24. In a telephone system, a battery, a “connector” comprising vertical and rotary line-relays permanently connected to one terminal of battery, an energizing circuit for said rotary-line-relay, a third relay by a single energization controlling said energizing circuit, and controlling the talking circuit, and switching means controlled by said line relays.
25. In a telephone system, a battery, a “connector” provided with vertical and rotary line-relays permanently connected to one terminal of battery, an energizing circuit for said rotary-line-relay, and a ringer-relay controlling said energizing circuit.
26. In a telephone system, a subscriber's telephone and auxiliary switching devices, a normally-open connection to ground controlled by said auxiliary switching devices, a relay controlling the continuity of said connection to ground, automatic switching machinery adapted to be operated by electrical impulses transmitted from the subscriber's station through the medium of said ground connection, and automatic means by which the guarding potential always established for a calling line is momentarily destroyed at the instant that a calling party-line subscriber completes connection with his own line to communicate with another subscriber on the same line.
27. In a telephone system, the combination of a subscriber's transmitter for sending the electrical impulses representing the called number, a ground connection adapted to cooperate with said transmitter in sending the said impulses, a relay adapted when energized to open the said connection to ground, automatic switching machinery adapted to be operated by the said electrical impulses, and automatic means by which the guarding potential always established for a calling line is momentarily destroyed at the instant that a calling party-line subscriber completes connection with his own line to communicate with another subscriber on the same line.
28. In a telephone system, the combination of subscriber's line-conductors, a normally-open connection to ground at the subscriber's station, means for closing said ground connection when the subscriber uses his telephone, a relay in said ground connection, another path to ground controlled by said relay, an energizing circuit for said relay including one of said line conductors, automatic switching means controlled over the grounded circuit controlled by said relay, and automatic means by which the guarding potential always established for a calling line is momentarily destroyed at the instant that a calling party-line subscriber completes connection with his own line to communicate with another subscriber on the same line.
29. In a telephone system, the combination of a subscriber's telephone and auxiliary switching devices, a relay associated with said telephone and auxiliary switching devices, grounded switching and ringing circuits controlled by said relay, a subscriber's line, a normally-open grounded energizing circuit for said relay, said energizing circuit including a conductor of said subscriber's line, and automatic means by which the guarding potential always established for a calling line is momentarily destroyed at the instant that a calling party-line subscriber completes connection with his own line to communicate with another subscriber on the same line.
30. In a telephone system, a subscriber's line, a plurality of subscribers' telephones and auxiliary switches connected with said line, a relay for each subscriber's telephone, ground connections controlled by said relays, signaling circuits including said ground connections, suitable circuits whereby an attempt to use any telephone serves to energize its allotted relay if any other subscriber is already in possession of the line, and automatic means by which the guarding potential always established for a calling line is momentarily destroyed at the instant that a calling party-line subscriber completes connection with his own line to communicate with another subscriber on the same line.
31. In a telephone system, the combination of a line, a plurality of telephones and subscribers' switching devices connected with said line, a relay for each telephone, normally-closed ground connections each connected with one terminal of the coil of the relay, normally-open connections extending between the other terminals of said relay-coils and one side of the said line, automatic switching means responsive to the grounding of the line, and automatic means by which the guarding potential always established for a calling line is momentarily destroyed at the instant that a calling party-line subscriber completes connection with the line.

his own line to communicate with another subscriber on the same line.

32. In a telephone system, the combination of a line, a plurality of subscribers' telephones and switching devices connected with said line, a relay for each telephone, switching and signaling circuits controlled by said relay, suitable circuits whereby the attempted use of any telephone serves to energize its allotted relay if the line is already in possession of another subscriber, locking devices for locking the relays in their energized positions, restoring means operative to restore any off-normal-relay to its normal condition when its allotted telephone is hung up, and automatic means by which the guarding potential always established for a calling line is momentarily destroyed at the instant that a calling party-line subscriber completes connection with his own line to communicate with another subscriber on the same line.

33. In a telephone system, the combination of a party-line having a plurality of subscribers' telephones thereon and auxiliary switching devices, a relay allotted to one of said telephones, an electrically-propelled and step-by-step-actuated switching machine provided with a line relay, an energizing circuit including the windings of said relays connected in series, means controlled by said relay for locking out the associated telephone if another telephone on the same line is using the line, and automatic means by which the guarding potential always established for a calling line is momentarily destroyed at the instant that a calling party-line subscriber completes connection with his own line to communicate with another subscriber on the same line.

34. In a telephone system, the combination of a party-line having a plurality of subscribers' telephones thereon and auxiliary switching devices, a relay allotted to one of said telephones, a connector provided with a line relay, an energizing circuit including the windings of said relays connected in series, means controlled by said relay for locking out the associated telephone if another telephone on the same line is using the line, and automatic means by which the guarding potential always established for a calling line is momentarily destroyed at the instant that a calling party-line subscriber completes connection with his own line to communicate with another subscriber on the same line.

35. In a telephone system, the combination of a party-line having a plurality of subscribers' telephones thereon and auxiliary switching devices, a relay allotted to one of said telephones, an electrically-propelled and step-by-step-actuated switching machine provided with a relay, an energizing circuit including the windings of said relays connected in series, means controlled

by said relay for locking out the associated telephone if another telephone on the same line is using the line, and automatic means by which the guarding potential always established for a calling line is momentarily destroyed at the instant that a calling party-line subscriber completes connection with his own line to communicate with another subscriber on the same line.

36. In a telephone system, the combination of a subscriber's telephone, a relay associated with said telephone, means controlled by said relay to prevent the subscriber from calling, a "connector" provided with a ringer-relay, a ringing-generator connected with said ringer-relay, an energizing circuit for said subscriber's relay, said energizing circuit being controlled at one point by the said ringer-relay, and automatic means by which the guarding potential always established for a calling line is momentarily destroyed at the instant that a calling party-line subscriber completes connection with his own line to communicate with another subscriber on the same line.

37. In a telephone system, the combination of a subscriber's telephone, a relay associated with said telephone, means controlled by said relay to prevent the subscriber from calling, a "first-selector" provided with a rotatable and endwise-shiftable switch-shaft, an energizing circuit for said relay adapted to be closed by the initial endwise movement of said shaft and automatic means by which the guarding potential always established for a calling line is momentarily destroyed at the instant that a calling party-line subscriber completes connection with his own line to communicate with another subscriber on the same line.

38. In a telephone system, the combination of a subscriber's telephone and auxiliary-switches, a relay allotted to and associated with said telephone, means controlled by said relay to prevent the subscriber from calling, a subscriber's line, a pair of relays bridged across the line, a battery having its non-grounded pole connected with said relays at a point between them, one side of the line being normally disconnected from one of said line-relays, means for closing connection between this side of the line and its allotted line-relay when the other line-relay is energized, a normally-open energizing circuit for said subscriber's line-relay, said energizing circuit including the side of the line which is normally disconnected from its line-relay, and automatic means by which the guarding potential always established for a calling line is momentarily destroyed at the instant that a calling party-line subscriber completes connection with his own line to communicate with another subscriber on the same line.

39. In a telephone system, the combination of a subscriber's switch-hook, a relay having normally-closed switch-contacts, means controlled by said relay to prevent the subscriber from calling, an armature adapted to open said contacts when the relay is energized, a locking device for catching and holding the armature in its attracted position, means for releasing the said armature when the switch-hook is restored to its normal position, and automatic means by which the guarding potential always established for a calling line is momentarily destroyed at the instant that a calling party-line subscriber completes connection with his own line to communicate with another subscriber on the same line.

40. In a telephone system, the combination of a subscriber's switch-hook, a relay having normally-closed switch-contacts, an armature adapted to open said contacts when the relay is energized, a locking device for catching and holding the armature in its attracted position, means for releasing the said armature when the switch-hook is restored to its normal position, a signaling circuit including said contacts, and automatic means by which the guarding potential always established for a calling line is momentarily destroyed at the instant that a calling party-line subscriber completes connection with his own line to communicate with another subscriber on the same line.

41. In a telephone system, the combination of a subscriber's switch-hook, a relay having normally-closed switch-contacts, an armature adapted to open said contacts when the relay is energized, a locking device for catching and holding the armature in its attracted position, means for releasing the said armature when the switch-hook is restored to its normal position, automatic switching machinery, switch-operating circuits including said contacts, and automatic means by which the guarding potential always established for a calling line is momentarily destroyed at the instant that a calling party-line subscriber completes connection with his own line to communicate with another subscriber on the same line.

42. In a telephone system, the combination of a subscriber's switch-hook, a relay associated with said switch-hook, means controlled by said relay to prevent the subscriber from calling, a grounded energizing circuit for said relay, means whereby said circuit is opened when the hook is raised from its normal position, and automatic means by which the guarding potential always established for a calling line is momentarily destroyed at the instant that a calling party-line subscriber completes connection with his own line to communicate with another subscriber on the same line.

43. In a telephone system, the combination of a subscriber's switch-hook, a relay associated with said switch-hook, switching and signaling circuits controlled by said relay, an energizing circuit for said relay, means whereby said energizing circuit is momentarily closed at one point and then opened at another point by the release of said switch-hook, and automatic means by which the guarding potential always established for a calling line is momentarily destroyed at the instant that a calling party-line subscriber completes connection with his own line to communicate with another subscriber on the same line.

44. In a telephone system, the combination of automatic switching machinery, subscriber's means for operating said switching machinery, controlling circuits for said switching machinery, a relay at the subscriber's station, said relay being adapted to control the said circuits, and automatic means by which the guarding potential always established for a calling line is momentarily destroyed at the instant that a calling party-line subscriber completes connection with his own line to communicate with another subscriber on the same line.

45. In a telephone system, the combination of a subscriber's line, a plurality of subscribers' telephones connected with said line, automatic switching machinery under the control of the subscribers, suitable grounded line-circuits for controlling said switching machinery, a relay at each subscriber's station, said relays being adapted to control the said circuits, and automatic means by which the guarding potential always established for a calling line is momentarily destroyed at the instant that a calling party-line subscriber completes connection with his own line to communicate with another subscriber on the same line.

46. In a telephone system, a "selector" provided with an operating magnet and a lamp, a normally-open circuit including said lamp and magnet in series, and automatic means by which the guarding potential always established for a calling line is momentarily destroyed at the instant that a calling party-line subscriber completes connection with his own line to communicate with another subscriber on the same line.

47. In a telephone system, a "selector" provided with a rotatable and endwise-shiftable switch-shaft, a magnet and means for operating said shaft, a visual signal, a normally-open circuit including said signal and magnet in series, means for closing said circuit upon the initial endwise movement of said shaft, and automatic means by which the guarding potential always established for a calling line is momentarily destroyed at the instant that a calling party-line subscriber completes connection with

his own line to communicate with another subscriber on the same line.

48. In a telephone system, a switching machine provided with an operating magnet, a side-switch-wiper and a visual signal, a normally-open circuit for said signal including said magnet and side-switch-wiper in series, and automatic means by which the guarding potential always established for a calling line is momentarily destroyed at the instant that a calling party-line subscriber completes connection with his own line to communicate with another subscriber on the same line.

49. In a telephone system, a battery, a "connector" provided with a pair of line-relays permanently connected to one terminal of battery, an energizing circuit for one of said relays, a third relay controlling the continuity of said energizing circuit at one point only, and automatic means by which the guarding potential always established for a calling line is momentarily destroyed at the instant that a calling party-line subscriber completes connection with his own line to communicate with another subscriber on the same line.

50. In a telephone system, a battery, a "connector" provided with a pair of line-relays permanently connected to one terminal of battery, a ringer-relay provided with normally-closed switch-contacts, an energizing circuit for one of said line-relays, said energizing circuit including the normally-closed switch-contacts, and automatic means by which the guarding potential always established for a calling line is momentarily destroyed at the instant that a calling party-line subscriber completes connection with his own line to communicate with another subscriber on the same line.

51. In a telephone system, a battery, a "connector" provided with vertical and rotary line-relays permanently connected to one terminal of battery, an energizing circuit for said rotary-line-relay, a third relay controlling said energizing circuit, and automatic means by which the guarding potential always established for a calling line is momentarily destroyed at the instant that a calling party-line subscriber completes connection with his own line to communicate with another subscriber on the same line.

52. In a telephone system, a battery, a "connector" provided with vertical and rotary line-relays permanently connected to one terminal of battery, an energizing circuit for said rotary-line-relay, a ringer-relay controlling said energizing circuit, and automatic means by which the guarding potential always established for a calling line is momentarily destroyed at the instant that a calling party-line subscriber com-

pletes connection with his own line to communicate with another subscriber on the same line.

53. In a telephone system, a visual signal lamp, an operating magnet, a side-switch contact-point, a side-switch-wiper normally in contact with said point, a couple of springs, an endwise-movable switch-shaft controlling said springs, and an energizing circuit for said lamp including said magnet and side-switch contact-point and side-switch-wiper and shaft-controlled-springs, said circuit being broken when the said side-switch-wiper leaves the said side-switch contact-point.

54. In a telephone system, a line, a "first-selector" allotted thereto, a side-switch-wiper, a grounded contact-point, a private-normal connected to "connector-private-bank-contacts" at one end, the other end terminating in said side-switch-wiper, said private-normal being adapted to be connected to ground when the said side-switch-wiper engages the said grounded contact-point, said private-normal being adapted also to be connected to ground at the "connector-private-bank-contacts" when the line calls back upon itself.

55. In a telephone system, a main battery, a "connector" having line-wipers, a talking circuit passing through said "connector" and divided into front and back sections by two condensers, one on each side of the talking circuit, the back section extending from the condensers to the said line-wipers and being free from connections to the said main battery, and means in the "connector" for opening said back section when the "connector" is restored.

56. In a telephone system, a line having a rotary and a vertical side, one or more sub-stations allotted to said line, a switch-hook at each sub-station, a "first-selector" in which said line terminates, the said rotary side being normally open at the "first-selector" and at the sub-stations, a condenser at each sub-station, said condensers being connected with a rotary side, and said rotary side and vertical side also being disconnected at each station whether the switch-hook is up or down.

57. In a telephone system, a "first-selector", a vertical-line-relay allotted to said "first-selector", a line of two conductors terminating in said "first-selector", one conductor known as the vertical-line-conductor and the other as the rotary-line-conductor, said vertical-line-relay being adapted to be energized by grounding the rotary-line-conductor.

58. In a telephone system, a station, a relay at said station, a private-normal-relay, a "connector-rotary-line-relay", and an energizing circuit for said station-relay

through said private-normal and rotary-line-relays, the line-relays being in series.

59. In a telephone exchange system, the combination of a telephone line, an automatic switch for said line, a plurality of substations on said line, means by which any substation may use said switch for calling other lines or each other, and automatic means individual to the line for preventing one substation from disturbing said switch while the latter is in use by another substation.

60. In a telephone exchange system, the combination of a telephone line, an automatic switch for said line, responsive to the different subscribers for calling each other or other lines, a plurality of substations on said line, means for preventing the locking out of the first substation that calls, and means individual to the line for locking out and preventing a second substation from disturbing said switch while the latter is in use by the first substation.

61. In a telephone exchange system, the combination of a telephone line, a plurality of substations on said line, an automatic switch responsive to the different subscribers for calling each other or other lines, means for preventing locking out of the first substation that calls, release mechanism for said switch, and means individual to the line for locking out and preventing a second substation from releasing said switch while the latter is in use by said first substation.

62. In a telephone exchange system, the combination of a telephone line, another line, automatic means for trunking the first line into connection with said other line, or into connection with itself, a plurality of substations on said first line, means for preventing the locking out of the first substation that calls, and means for locking out and preventing a second substation on the same line from disturbing said automatic trunking means while the latter is in use by said first substation.

63. In a telephone exchange system, the combination of a party telephone line, a plurality of substations on said line, automatic means for establishing connection between said party line and some other line, releasable by any calling subscriber on the line, and automatic means individual to the line for preventing one subscriber on the party-line from interfering with a connection previously established over said party-line by another subscriber on the same line.

64. In a telephone exchange system, the combination of a subscriber's telephone line, an automatic switch individual to said line, a line relay for controlling said switch, a station on said line, a magnet for said station having an energizing circuit including said relay, said relay normally disconnected

from said line to maintain said circuit open, 65 and means for connecting the relay with the line to bring the same under the control of the subscriber.

65. In a telephone exchange system, the combination of a subscriber's telephone line, 70 automatic trunk-selecting machinery, trunk lines to be selected by said machinery, a line relay individual to said line by which the subscriber controls the operation of said machinery, a station on said line, a magnet for 75 said station having an energizing circuit including said relay, said relay normally disconnected from said telephone line to maintain said circuit open, and means for connecting the relay with the line to bring the 80 same under the control of the subscriber.

66. In a telephone exchange system, the combination of a subscriber's telephone line, a pair of line relays connected in a bridge across the said telephone line, said bridge 85 being normally open, a station for said line, a magnet for said station, an energizing circuit including one of said relays, means operated by the other relay for connecting the first relay with the line, thereby bringing 90 the same under the control of the subscriber and closing said energizing circuit.

67. In a telephone exchange system, the combination of a subscriber's telephone line, a line relay therefor normally disconnected 95 from said line, a station for said line, a magnet for said station, an energizing circuit for said magnet including said relay, means including another relay for connecting the said first-mentioned relay with the line to 100 bring the same under the control of the subscriber and close said circuit, and automatic switch mechanism controlled by said relays.

68. In a telephone exchange system, the combination of a line, a pair of relays 105 bridged across said line, said bridge being normally open, one relay normally connected with and the other relay normally disconnected from said line, a station for said line, a magnet for said station, an energizing circuit for said magnet including said other relay, means operated by the one relay for closing connection between the other relay and the line to bring said other relay under the control of the subscriber and close said 110 circuit, and switching means controlled by said other relay.

69. In a telephone exchange system, the combination of a line, a selector therefor, a pair of relays for said selector, said relays 120 bridged across the said line, said bridge being normally open to normally retain one relay in an inoperative relation to the line, a station for said line, a magnet for said station, an energizing circuit for said magnet including said one relay, and a switch operated by the selector upon the energizing of the other relay for closing said bridge to 125

bring the one relay under the control of the subscriber and close said circuit.

70. In a telephone exchange system, the combination of a line circuit, an automatic trunk selector, trunks leading from, said selector, and a pair of line relays for said selector, said relays bridged across the said line circuit, said bridge being normally open, one line relay normally connected with 10 and the other relay normally disconnected from the said line circuit, a station for said line, a magnet for said station, an energizing circuit for said magnet including said other relay, the said selector provided with a 15 switch adapted to be closed by the energizing of the one relay to restore the continuity of said bridge and thereby bring said other relay under the control of the subscriber and close said circuit.

71. In a telephone exchange system, the combination of a subscriber's telephone line, a line relay individual thereto and normally disconnected therefrom, a station for said line, a magnet for said station, an energizing 25 circuit for said magnet including said relay, and means by which the line is employed for bringing the said relay under the control of the subscriber and for closing said circuit.

72. In a telephone system, a first selector 30 switch, a side switch therefor, a line for said selector, a station for said line, a magnet for said station, an energizing circuit for said magnet including said side switch, and a talking circuit comprising said line, said 35 talking circuit normally open between the line and the side switch to prevent said magnet from energizing before the switch operates.

73. In a telephone system, the combination 40 of a subscriber's line, a plurality of subscribers' telephones connected with said line, automatic switching machinery under the control of the subscribers, suitable grounded line circuits for controlling said 45 switching machinery, and a relay at each subscriber's station excluded from the path of voice currents and controllable by another subscriber, said relays being adapted to control the said circuits to prevent use of 50 said switches by one subscriber when they are in use by another on the same line.

74. In a telephone system, the combination 55 of a party-line having a plurality of subscribers' telephones thereon and auxiliary switching devices, a relay allotted to one of said telephones, an electrically-propelled and step-by-step-actuated switching machine provided with a line relay, an energizing circuit including the windings of 60 said relays connected in series, and means controlled by said relay for locking out the associated telephone if another telephone on the same line is using the line.

75. In a telephone system, the combination 65 of a subscriber's station, a relay asso-

ciated with said station, an automatic switch provided with a movable member controllable from said station, an energizing circuit for said relay adapted to be closed by the initial movement of said member, 70 and means controlled by said relay for preventing said subscriber's station from controlling said selector.

76. A telephone system comprising a party-line, a plurality of substations thereon, a lock-out relay at each substation, a hook-switch at each substation, and an energizing circuit for each relay, each energizing circuit being provided with two switch-points controlled and actuated by the hook- 80 switch of the same substation.

77. In a telephone system, a subscriber's line, a trunk line, means for extending a talking connection from said subscriber's line over said trunk line, a ground connection 85 for preventing a connection being made with said subscriber's line, and a relay for controlling said ground connection.

78. In a telephone system, a party line, 90 relays for the substations thereof, said substations being in multiple, automatic switches controllable over the said line, and means whereby said relays preclude interference between the subscribers in the use of said switches.

79. In an automatic telephone system, a party line, relays for the substations thereof, said substations being in multiple, hook switches controlling the circuits of said relays, an automatic switch, and means at said 100 substations for controlling said switch for extending connection from said party line.

80. In a telephone system, a telephone line having one side thereof normally open at the exchange or central station, means 105 controlled by a subscriber on said line for closing said normally open connection in the talking circuit, a relay provided with an energizing circuit which includes the said normally open connection, a vertical and rotary switch shaft, and operating circuits controlled by said relay for controlling said shaft.

81. A telephone system comprising a party-line, a plurality of substations thereon, a lock-out relay at each substation, a hook-switch at each substation, trunking switches having vertical motion to select groups and rotary motion to automatically 115 select an idle trunk in the selected group, and an energizing circuit for each relay, each energizing circuit being provided with two switch points controlled by the hook-switch of the same substation, said relay 120 controlling the use of said switches.

82. In a telephone system, a party-line having a plurality of substations thereon, a first selector common to said substations, a normally open line conductor adapted to be closed by the operation of said first selec- 130

- tor, and a relay adapted to be energized over said normally open line conductor after the subscriber at another substation has operated the common first selector and thereby closed the normally open line conductor. 5
83. In a telephone system, a telephone line, a plurality of substations for said line, a lock-out relay for each telephone for preventing one telephone from interfering with another, a separate energizing circuit for each relay, and an operating circuit for each telephone, the lock-out relay of each telephone controlling the operating circuit of its telephone. 10
84. In a telephone system, a telephone line, a plurality of sub-stations for said line, a lock-out relay for each telephone for preventing one telephone from interfering with another, a separate energizing circuit for each relay, and an operating circuit for each telephone, the lock-out relay of each telephone controlling the operating circuit of its telephone, and a switch associated with the line controlling the circuits of all the 25 lock-out relays.
85. In a telephone system, a telephone line, a plurality of sub-stations for said line, a lock-out relay for each telephone for preventing one telephone from interfering with another, a separate energizing circuit for each relay, and an operating circuit for each telephone, the lock-out relay of each telephone controlling the operating circuit of its telephone, and a progressively movable switch associated with the line controlling the circuits of all the lock-out relays. 30
86. In a telephone system, a telephone line, a plurality of substations for said line, a lock-out relay for each telephone for preventing one telephone from interfering with another, a separate energizing circuit for each relay, and an operating circuit for each telephone, the lock-out relay of each telephone controlling the operating circuit of its telephone, and a switch associated with the line and controlled over the operating circuit at each telephone for controlling the circuits of all the lock-out relays. 45
87. In a telephone system, a telephone line, a plurality of sub-stations for said line, a lock-out relay for each telephone for preventing one telephone from interfering with another, a switch associated with said line controlling the energizing circuits of said 50 relays, and means at each telephone for operating said switch to prepare an energizing circuit for a plurality of said relays.
88. In a telephone system, a telephone line, a plurality of sub-stations for said line, a lock-out relay for each telephone for preventing one telephone from interfering with another, a separate energizing circuit in each telephone for each lock-out relay, means controlled at each telephone for rendering the relay of said telephone inoper- 55
- ative during a call and for permitting any one of the other relays to be operated during the same call. 60
89. In a telephone system, a line, a plurality of telephones for said line, a lock-out magnet at each telephone controlling an operating circuit for its telephone, a progressively movable switch for the line, an energizing circuit at each telephone for the lock-out magnet associated therewith, a branch common to all of said circuits and controlled by said switch, means at each telephone for operating said switch to close said common branch to prepare an energizing circuit for the lock-out magnets associated with said line, whereby they may be operated during a call, and means for rendering the operating magnet of the calling telephone inoperative during the same call. 65
90. In a telephone system, a line, a plurality of telephones for said line, a lock-out mechanism for each telephone for preventing the interference of its telephone with any other telephone that is calling, each of said lock-outs being normally inoperative, whereby when a telephone is operated its lock-out does not operate, and means controlled when said telephone is operated to render the lock-out mechanism operable whereby when any other telephone is operated its lock-out is operated. 70
91. In a telephone system, a line, an automatic switch for said line, a plurality of telephones for said line, an impulse sender for each telephone for operating said switch over said line, an electromagnetic lock-out mechanism for each telephone for rendering its impulse sender inoperable. 75
92. In a telephone system, a line, an automatic switch for said line, a plurality of telephones for said line, an impulse sender for each telephone for operating said switch over said line, an electromagnetic lock-out mechanism for each telephone for rendering its impulse sender inoperable after any other telephone on the line is operated. 80
93. In a telephone system, a line, an automatic switch for said line, a plurality of telephones for said line, an impulse sender for each telephone for operating said switch over said line, an electromagnetic lock-out mechanism for each telephone for rendering its impulse sender inoperable only after another telephone is operated. 85
94. In a telephone system, a line, an automatic switch for said line, a plurality of telephones for said line, an impulse sender for each telephone for operating said switch over said line, an electromagnetic lock-out device for each telephone, a circuit for each lock-out controlled by the switch, each lock-out when operated rendering the impulse sender of its telephone inoperative. 90
95. In a telephone system, a line, an automatic switch for said line, a plurality of 120
- 125
- 130

5 telephones for said line, an impulse sender for each telephone for operating said switch over said line, an electromagnetic lock-out device for each telephone, a circuit for each lock-out controlled by the switch, each lock-out when operated rendering the impulse sender of its telephone inoperative after any other telephone has operated the switch.

- 10 96. In a telephone system, a line, an automatic switch for said line, a plurality of telephones for said line, an impulse sender for each telephone for operating said switch over said line, an electromagnetic lock-out device for each telephone, a circuit for each lock-out controlled by the switch, each lock-out when operated rendering the impulse sender of its telephone inoperative only after any other telephone has operated the switch.
- 15 97. In a telephone system, a line, an automatic switch for said line, a plurality of telephones for said line, an impulse sender for each telephone for operating said switch over said line, an electromagnetic lock-out device for each telephone, a circuit for each lock-out controlled by the switch and the telephone.

20 98. In a telephone system, a line, an automatic switch for said line, a plurality of telephones for said line, an impulse sender for each telephone for operating said switch over said line, an electromagnetic lock-out device for each telephone, a circuit for each lock-out controlled by the switch and the telephone only after another telephone has operated the switch.

25 99. In a telephone system, a line, an automatic switch for said line, a plurality of telephones for said line, an impulse sender for each telephone for operating said switch over said line, an electromagnetic lock-out mechanism for each telephone for rendering its impulse sender inoperative, a normally inoperative circuit common to all said lock-out devices controlled by said switch and rendered operative when the switch is operated, and an individual branch for each lock-out controlled by its associated telephone to operate the lock-out after the switch has operated.

30 100. In a telephone system, a line, an automatic switch for said line, a plurality of telephones for said line, an impulse sender for each telephone for operating said switch over said line, an electromagnetic lock-out mechanism for each telephone for rendering its impulse sender inoperative, and a normally open circuit common to all said lock-out devices controlled by said switch to close the same when the switch is operated, and an individual branch for each lock-out controlled by its associated telephone to operate the lock-out after the switch has closed the circuit.

35 101. In a telephone system, a line, an au-

tomatic switch for said line, a plurality of telephones for said line, an impulse sender for each telephone for operating said switch over said line, an electromagnetic lock-out mechanism for each telephone for rendering its impulse sender inoperative, a normally open circuit common to all said lock-out devices controlled by said switch to close the same when the switch is operated, and a normally open individual branch for each lock-out mechanism controlled by its associated telephone to close an energizing circuit for the lock-out mechanism after the switch is operated.

40 102. In a telephone system, a line, an automatic switch for said line, a plurality of telephones for said line, an impulse sender for each telephone for operating said switch over said line, an electromagnetic lock-out mechanism for each telephone for rendering its impulse sender inoperative, a normally inoperative circuit common to all said lock-out devices controlled by said switch and rendered operative when the switch is operated, and an individual branch for each lock-out controlled by its associated telephone to operate the lock-out after the switch has operated, said common circuit comprising the line.

45 103. In a telephone system, a line, an automatic switch for said line, a plurality of telephones for said line, an impulse sender for each telephone for operating said switch over said line, an electromagnetic lock-out mechanism for each telephone for rendering its impulse sender inoperative, and a normally open circuit common to all said lock-out devices controlled by said switch to close the same when the switch is operated, and an individual branch for each lock-out controlled by its associated telephone to operate the lock-out after the switch has closed the circuit, said common circuit comprising the line.

50 104. In a telephone system, a line, an automatic switch for said line, a plurality of telephones for said line, an impulse sender for each telephone for operating said switch over said line, an electromagnetic lock-out mechanism for each telephone for rendering its impulse sender inoperative, a normally open circuit common to all said lock-out devices controlled by said switch to close the same when the switch is operated, and a normally open individual branch for each lock-out mechanism controlled by its associated telephone to close an energizing circuit for the lock-out mechanism after the switch is operated, said common circuit comprising the line.

55 105. In a telephone system, a line, an automatic switch for said line, a plurality of telephones for said line, an impulse sender for each telephone for operating said switch over said line, an electromagnetic lock-out

mechanism for each telephone for rendering its impulse sender inoperable, a normally inoperative circuit common to all said lock-out devices controlled by said switch and 5 rendered operative when the switch is operated, and an individual branch for each lock-out controlled by its associated telephone to operate the lock-out after the switch has operated, said common circuit comprising 10 only one side of the line.

106. In a telephone system, a line, an automatic switch for said line, a plurality of telephones for said line, an impulse sender for each telephone for operating said switch 15 over said line, an electromagnetic lock-out mechanism for each telephone for rendering its impulse sender inoperable, and a normally open circuit common to all said lock-out devices controlled by said switch to 20 close the same when the switch is operated, and an individual branch for each lock-out controlled by its associated telephone to operate the lock-out after the switch has closed the circuit, said common circuit comprising 25 only one side of the line.

107. In a telephone system, a line, an automatic switch for said line, a plurality of telephones for said line, an impulse sender for each telephone for operating said switch 30 over said line, an electromagnetic lock-out mechanism for each telephone for rendering its impulse sender inoperable, a normally open circuit common to all said lock-out devices controlled by said switch to close the 35 same when the switch is operated, and a normally open individual branch for each lock-out mechanism controlled by its associated telephone to close an energizing circuit for the lock-out mechanism after the 40 switch is operated, said common circuit comprising only one side of the line.

108. In a telephone system, a line, an automatic switch for said line, a plurality of telephones for said line, an impulse sender 45 for each telephone for operating said switch over said line, an electromagnetic lock-out mechanism for each telephone for rendering its impulse sender inoperable, a circuit common to all of said lock-out mechanisms controlled by said switch, and an individual 50 branch for each lock-out mechanism controlled by its associated telephone.

109. In a telephone system, a line, an automatic switch for said line, a plurality of telephones for said line, an impulse sender for each telephone for operating said switch over said line, an electromagnetic lock-out 55

mechanism for each telephone for rendering its impulse sender inoperable, a circuit common to all of said lock-out mechanisms controlled by said switch, and an individual branch for each lock-out mechanism controlled by its associated telephone, said common circuit individual to the line. 60

110. In a telephone system, a line, an automatic switch for said line, a plurality of telephones for said line, an impulse sender for each telephone for operating said switch over said line, an electromagnetic lock-out mechanism for each telephone for rendering 70 its impulse sender inoperable, a circuit common to all of said lock-out mechanisms controlled by said switch, and an individual branch for each lock-out mechanism controlled by its associated telephone, said common circuit individual to one side of the line. 75

111. In a telephone system, a line, an automatic switch for said line, a plurality of telephones for said line, an impulse sender for each telephone for operating the switch 80 over said line, an electromagnetic lock-out mechanism for each telephone, for rendering its impulse sender inoperable, a circuit common to all of said lock-out mechanisms controlled by said switch, an individual 85 branch circuit for each lock-out mechanism controlled by its telephone whereby when the first telephone comes on the line to operate the switch its lockout does not operate, and whereby the other lock-out devices are 90 rendered operable when any other telephone is brought on the line, whereby said other telephone is prevented from interfering, if its impulse mechanism is operated, with the connection of the telephone previously on 95 the line.

112. A telephone system comprising a party line, a plurality of substations on said line, a normally depressed switch hook at each substation, a relay associated with each 100 switch hook, subscriber controlled automatic means for extending a connection, circuits controlled by said relays, and means whereby the taking down of any receiver will energize the relay of the same substation if 105 said automatic means is in an operated condition.

Signed by me at Chicago, Cook county, Illinois, this 16th day of November, 1905.

TALBOT G. MARTIN.

DISCLAIMER.

1,151,544.—*Talbot G. Martin*, Chicago, Ill. NON-INTERFERING EXTENSION PARTY-LINE TELEPHONE SYSTEM. Patent dated August 24, 1915. Disclaimer filed June 28, 1920, by the patentee, the assignee, *Automatic Electric Company*, consenting.

Enters this disclaimer—

“To claim 77 in said specification, which is in the following words, to wit:

“77. In a telephone system, a subscriber's line, a trunk line, means for extending a talking connection from said subscriber's line over said trunk line, a ground connection for preventing a connection being made with said subscriber's line, and a relay for controlling said ground connection.”
